UNITED STATES PATENT OFFICE

JOHN WICKS, OF OAK PARK, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

MULTIOFFICE TELEPHONE SYSTEM

Application filed September 28, 1929, Serial No. 395,882. Renewed March 28, 1932.

This invention relates to multi-office telephone systems in general but is concerned more particularly with multi-office automatic telephone systems of the so called "inverted" type, in which talking and holding current is supplied from the first selector instead of from the connector. A system of this type is shown in the copending application of J. Wicks, Serial No. 297,611, filed 5 August 6, 1928, now Patent No. 1,778,204, Oct. 14, 1930, of which this invention may be considered as an improvement.

The invention has for its broad objects the provision of new and improved circuits and switches for use in systems of the above type, for making such systems more efficient and practical, and for providing additional service features.

One feature of the invention is a tandem toll service trunking arrangement in which two-way inter-office trunks are utilized for both local and toll service. This arrangement, incidentally, requires new combination local and toll selectors and connectors which 20 also form a part of the invention. The trunks connecting the toll board and the tandem office are likewise for two-way traffic and serve both as toll completing and toll recording trunks. In addition, the system 25 is arranged for preferred toll service, i. e. toll calls may be completed to lines engaged in local connections.

Another feature of the invention is the 30 retractive ringing arrangement. This permits the subscriber to signal an extension station on the same line as is done in party line systems. The retractive ringing apparatus is also useful for testing and adjusting 35 substation ringers, permitting this to be done by a repair man at the sub-station without any assistance from the central office.

Another feature is the arrangement for 40 transmitting alarm signals from an unattended exchange to an operator over the regular inter-office and toll board trunks. The signalling apparatus, moreover, does not interfere with regular inter-office traffic since 45 the trunk being used for signalling purposes 50 is still accessible to the automatic switches

of the exchanges and is available for local or toll calls.

The foregoing features together with others not specifically mentioned, will be described in detail hereinafter, reference being had to the accompanying drawings.

For the purpose of this description, it has been chosen to show the application of the invention in a telephone system comprising two automatic offices and a manual toll office. It is to be understood, however, that the use of the invention is not limited to the particular arrangement shown. The two automatic offices will be referred to herein-after as office "A" and office "B," respectively, and the manual or toll office will be referred to as the toll board. The automatic offices are connected by two-way trunks. Office "A" is also connected with the toll board by two-way toll completing and toll recording trunks and serves as the tandem switching center for all toll calls in the system. In the system used for illustration, the automatic offices are of the one-thousand line type, although it is obvious that offices of any other size may be employed. In order to provide a universal numbering system, the numbering is on a four digit basis and the local first selectors are arranged to cancel the first digit on local calls. It is further assumed that the two automatic offices are normally unattended and provision is made for extending alarm signals from these offices to the toll board over the regular service trunks. The alarm from each office takes a 55 different route to the operator who is thus advised of the particular office in which the alarm originates.

Referring now to the accompanying drawings comprising Figs. 1 to 10, inclusive, Figs. 1 to 9, inclusive, show by means of the usual circuit diagrams a sufficient amount of equipment in a telephone system employing the invention, to permit the invention to be readily described and understood. Fig. 10 is a layout diagram showing the manner with which the sheets of drawings should be arranged in order to show the interrelation of the various circuits.

In Fig. 1 is shown a subscriber's line serv-

ing sub-station T and extension station T1 and terminating in rotary line switch LS. The sub-stations are of the usual automatic type. The line switch LS is of the well known rotary type, having no normal or home position, and is provided with an extra wiper for metering purposes. The line switch has access to local first selectors of which one selector SR is shown. Selector SR mechanically is an ordinary two motion Strowger type switch. The circuit of this selector is of the type required in the inverted system and the switch is arranged to supply battery for the control loop as well as talking battery for both the calling and called subscribers. Selector SR has access by way of its wipers and banks to local connectors, reverting ringing relay groups, trunks leading to the toll board, and trunks extending to the other automatic exchanges of the system, such as trunks to the exchange "B". The line switch and selector in Fig. 1 are in exchange "A".

Fig. 2 shows a revertive ringing relay group RC accessible to local first selectors of the automatic exchange A. This relay group is arranged to ring back on the calling line, to signal the extension station on that line.

In Fig. 3 is shown a combination local and toll connector C and the sub-station T2 terminating a subscriber's line. Mechanically the connector is a Strowger type, vertical and rotary switch similar to selector SR of Fig. 1. The circuit, however, is arranged to operate in an inverted system with selectors such as selector SR.

Fig. 4 shows a trunk relay group RCT terminating a combined recording and completing trunk connecting the toll board and office A. The dialling cord DC is used for extending calls over these trunks to the automatic exchange. Incoming calls are answered by means of the usual operator's answering cord AC of which only a part is shown. Toll calls are also completed by the answering cord or by a regular toll cord (not shown).

Fig. 5 shows a toll transmission selector TTS in which the trunks from the toll board terminate at the automatic exchange. This switch is also of the usual Strowger, vertical and rotary type and mechanically is very similar to selector SR. A special feature of this switch is the arrangement for switching through on tandem toll calls as will be explained in later paragraphs. The switch feeds holding battery and talking current for the called subscriber and the operator in the same manner as local selector SR.

In Fig. 6 is shown an incoming selector repeater ISR terminating a two way trunk connecting two automatic offices. Mechanically, this switch is similar to selector SR. The circuit, however, is modified to adapt it for trunk service.

Fig. 7 shows an alarm signal relay group

ASR for transmitting alarm signals indicating unstandard conditions in the automatic exchanges to the toll operator. This relay group actually comprises two distinct operating elements. One of these elements is associated with an inter-office trunk such as the trunk terminating in selector ISR of Fig. 6 and operates to relay alarm signals over this trunk, to the toll operator by way of a toll recording trunk. The other element is for transmitting alarm signals from the "A" office to the toll operator over one of the toll recording trunks. The alarm signal apparatus shown is not the complete alarm system of an automatic exchange. Two fuse alarms only have been shown as this permits a clear understanding of the operation of the apparatus. It may be noted here that the object in classifying the alarm signals as is done in this instance is to give the operator an idea of the seriousness of the trouble in the automatic exchange. Certain unstandard conditions will tie up only a single piece of apparatus, and thus not effect the services of the exchange to any great extent, while other unstandard conditions may completely interrupt the service of the exchange. In the latter case, it is necessary to send out a repairman immediately to restore the service.

Fig. 8 shows an incoming selector ISR1 terminating a two-way trunk from the tandem automatic office, such as the trunk terminating in selector ISR of exchange "A". This selector is for both toll and local service. Mechanically and electrically, selector ISR1 is similar to selector ISR with certain modifications to adapt it for combination use as will be explained in later paragraphs. This selector has access only to connectors in the B office.

In Fig. 9 is shown alarm signal relay group ASR1 corresponding to the local alarm relays in relay group ASR, Fig. 7. The alarm signal apparatus shown is similar to that shown in Fig. 7. In Fig. 9 are also shown the local selector S1 and connector C1. These switches are shown only in skeleton form and are identical with the selector SR and connector C of Figs. 1 and 3, respectively. T3 and T4 are two ordinary automatic sub-stations similar to sub-station T. The sub-station T3 terminates in line switch LS1 which is similar to line switch LS of Fig. 1.

Local calls in the automatic exchange are made by dialling a four digit number. For example, sub-station T in calling sub-station T2 on initiating the call is connected with a selector such as selector SR by way of line switch LS. The first digit dialled, in this case the digit four, causes selector SR to raise its wipers opposite the fourth level and then restore to normal. The second digit again causes the selector SR to raise its wipers opposite the called level in which local connectors such as connector C are accessible, where-

in the connection is extended to such local connectors. The two final digits operate the connector to the contacts of the called line which is then signalled in the usual way by the 5 connector. In making an inter-office call, sub-station T will dial the digit of the wanted office, in this case the digit 3, and selector SR will operate to select a trunk to the "B" office. The second digit of the called number 10 will operate selector ISR1 to a local level where a trunk extending to a local connector, such as connector C1, will be selected. The two final digits of the number operate connector C1 to the contacts of the called line 15 which is then signalled in the usual way by the connector.

It will be noted that the two sub-stations 20 namely T and T1 are associated with one subscriber's line. T1 is shown to be an extension station from which calls may be extended or answered. It may in some cases be desirable to signal between sub-stations T and T1. In this case the calling sub-station being extended to a selector, such as selector SR, 25 will operate this switch to the level in which the retractive ringing relay group RC is accessible. The selector is arranged to switch through on this level, disconnecting the regular battery feeding bridges. When the receiver is hung up at the calling sub-station, 30 the relay group RC will transmit ringing current over the calling line to ring the bells at both the regular sub-station and the extension sub-station on the line. Selector SR, 35 however, does not release under these conditions but is held locked up by the relay group. When either party answers, the ring is cut off and when the receivers at the two sub-stations are finally replaced, the equipment all 40 returns to normal in the usual way. In testing a sub-station ringer, a similar procedure is followed by the repair man.

Toll calls for subscribers in either automatic exchange are extended manually from 45 the toll board. A talking connection between the incoming toll line (not shown) and the toll completing trunk such as the trunk RCT of Fig. 4 is set up by means of the usual toll or answering cord AC. The operator then 50 inserts the dialling cord, such as cord DC, into the dialling jack of the selected trunk and dials the last three digits of the called number if the subscriber is in exchange "A", or the complete number if in the exchange 55 "B". Toll transmission selector TTS responds to the first digit and selects a combination connector, such as connector C in exchange "A". This connector is then operated responsive to the last two digits to 60 select the called line. The connector signals the called line under control of the operator at the manual board. In case the called line is busy in either a local or a toll call, the toll operator is given a distinctive signal to 65 that effect. If busy in a local call, the oper-

ator may cut in and talk to the subscribers on the wanted line and inform them that a toll call is waiting. In case the line wanted is not released immediately, the operator may disconnect the call in which case the toll call will be extended through to the line. The operator cannot cut in, however, when the wanted line is busy in a toll call. To call a subscriber in the "B" office, the operator dials the second exchange digit, in this case 70 the digit 3, and toll transmission selector TTS, selects a trunk to exchange "B" terminating in the selector such as ISR1. The second digit operates selector ISR1 to a local level and extends the call to a combination connector such as connector C1. Connector C1 responds to the last two digits to extend the call in the same manner as connector C. Since the inter-office trunk is used for both toll and local calls, it is necessary that certain switching operations take place in order 75 to provide the proper service for the different types of calls. Such switch-over operation changing from local to toll operation is brought about by a reversal of battery over the trunk when the call is extended by way of the toll transmission selector.

Subscribers in each exchange may reach 80 the toll operator over one of the combination toll completing and toll recording trunks by dialling a recording code such as the two digits 40, selected in this case by way of illustration. This code dialled from a sub-station in office "A" first operates the first selector to a local level from which the selector drops back and cancels the digit, and in response to the second digit extends the call over the "O" level to a trunk such as the one extending to trunk group RCT. This code dialled from a sub-station in exchange 85 "B" causes a local selector S1 to select a trunk such as the one extending to incoming selector ISR in exchange "A" which in turn responds to the second digit and extends the call to the operator in the usual way.

Alarm signals in the automatic exchanges 90 cause the operation of one of the relay groups ASR or ASR1. The former relay group connects a potential to the toll recording trunk in order to signal the operator at the toll board. In the case of an alarm signal in the "B" office, the alarm relay group in that office extends the signal over an inter-office trunk to the alarm relay group in the "A" office which in turn relays the call to the operator. A different trunk is used to forward the alarm signals from the different offices in order to indicate the origin of the 95 call to the operator.

The alarm signal equipment is so arranged 100 that a regular call may seize the inter-office trunk at any time when a signal is being transmitted. The signal equipment is temporarily disconnected and at the completion 105

of the call it reoperates to again forward the signal to the toll operator.

Having described briefly the operation of the equipment and the apparatus involved, a 5 detailed description of the various connections will now be given.

Call from sub-station T to sub-station T2

When the subscriber at sub-station T lifts 10 the receiver, a loop including the impulse contacts of the calling device at sub-station T is closed for relay 5 of the associated line switch LS. This circuit extends from ground, armature 11, line conductor 3, 15 through the calling subscriber's telephone, line conductor 2, armature 8, winding of relay 5, to battery. Relay 5 operates, closes a circuit for relay 4 at armature 13, and at armature 12, closes the usual testing circuit by 20 connecting the test wiper 16 between switching relay 4 and stepping magnet 6. In case the trunk on which the wipers are standing is busy, wiper 16 will encounter a ground which shunts relay 4 and causes the stepping 25 magnet to operate and advance the wipers to the next set of contacts. This operation will be repeated as long as wiper 16 encounters grounded contacts. Magnet 6 opens its own circuit at interruptor contact 30 18 at each step. When an idle trunk is found which will be assumed to be the trunk terminating in selector SR, there will be no ground on the test contact engaged by wiper 16 and relay 4 being no longer shunted, will 35 operate. The calling line loop will be extended by way of armatures 8 and 11 and wipers 14 and 17, to the line relay of selector SR. The release trunk conductor will be switched over from the upper to the lower 40 terminal of relay 4 to provide a holding circuit for that relay after relay 5 releases. The metering conductor extending from wiper 15 is connected to meter 7 at armature 9. The circuit of relay 5 is opened at 45 armatures 8 and 11 and that relay, being slow-to-release, maintains its armatures operated long enough for the selector to return a holding ground over the release trunk to hold relay 4 operated. When the calling 50 line is extended to the selector, a circuit is closed for line relay 101 which may be traced from battery, upper winding of relay 102, left-hand coil of relay 101, armatures 141 and 127, upper talking conductor, wiper 14 and armature 8 of line switch LS, line conductor 2, through the loop at the calling sub-station, line conductor 3, armature 11 and wiper 17 of the line switch, lower talking conductor, armature 131, right-hand coil of 55 relay 101, lower winding of relay 102, to ground. Relay 101 operates and closes a circuit from ground, armature 122, winding of relay 108, windings of relay 107, to battery, and in parallel therewith, through the interrupter contacts 176, armature 158, wind-

ing of magnet 112 to battery. Relay 108 operates in the above circuit, but due to the high resistance of this relay, relay 107 and magnet 112 do not operate at this time. It may be noted that relay 102 does not operate 70 over the loop circuit traced for relay 101, because its windings are arranged to oppose each other. Relay 108 on operating, connects ground to the release trunk conductor at armature 147 to hold up relay 4 as previously mentioned. At armature 146 an alternate circuit is closed for relay 101 independent of armature 141. At armature 148 a short circuit for relay 108 is closed which circuit will also serve to operate relay 107 75 and vertical magnet 112. Relay 101 also closes a circuit from battery, upper winding of relay 102, upper winding of relay 103, armature 121, normally closed contacts controlled by armatures 127 and 155, respectively, upper winding of relay 106, to ground. Relays 103 and 106 operate in series over the 80 above circuit. The resistance of relay 106 is high enough so that relay 102 is not unbalanced and consequently does not operate 85 at this time. Relay 103 upon operating opens a point in the release circuit at armature 125 and closes a point in the holding circuit of relay 106 at armature 126. Relay 106 upon operating closes a point in the temporary holding circuit of relay 103 at armature 134, connects dial tone to the upper talking conductor of the selector at armature 135, opens a point in the busy tone circuit at armature 136, and completes its own locking 90 circuit at armature 139. This latter circuit may be traced from ground at armature 126, armature 139, lower winding of relay 106, to battery, and serves to maintain the relay in 95 operated position until such time as relay 103 restores. The dial tone is audible to the calling subscriber who is informed thereby that he has been connected with a first selector and that the dialling may proceed. 100

It has been assumed for the purpose of 105 describing the operation, that the number of the called line is 4422. A calling subscriber now proceeds to dial this number by operating the calling device at the sub-station. The calling loop is interrupted correspondingly, and relay 101 responds by retracting its armatures at each interruption of the circuit. At each impulse a circuit is closed from battery, upper winding of relay 102, upper winding of relay 103, normally closed contact controlled by armature 121, armatures 150, 144, and 134, resistance 114, to ground. Relay 103 holds its armatures in operated position 110 over the above circuits during the transmission of impulses. Resistance 114 is of such a value that the relay 102 is not unbalanced and consequently does not operate. Relay 101 by retracting its armature 122 short circuits relay 108, and a circuit is closed from ground, armature 148, contacts controlled by 115 120 125 130

5 armature 122, through the winding of relay 107 to battery, and in parallel therewith, through interrupter contacts 176, armature 158, vertical magnet 112 to battery. The vertical magnet operates over the above circuit and raises the wipers one step in response to each impulse from relay 101. Relay 107 operates in parallel with the vertical magnet and maintains its armatures actuated throughout the series of impulses due to its slow-releasing characteristic. It will be noted that relay 107 is connected in series with relay 108, during the time relay 101 is operated. As previously stated the resistance of relay 108 is such that relay 107 will not operate in series therewith, nor will relay 107 remain operated when connected in series. This connection, however, causes the relay 107 to become slow in releasing. Since the digit 4 was dialled, relay 101 drops back four times and transmits four impulses to magnet 112, which raises the wipers opposite the fourth level of bank contacts. On the first vertical step of the wipers, off-normal contacts 116 operate and disconnect the dial tone from the calling line, contacts 117 close a point in the release circuit, and contacts 118 close a point in the circuit of the rotary magnet. When the wipers reach the fourth level, shaft springs 120 operate. These springs are adjustable and are set to operate on the particular level from which it is desired that the selector shall release.

35 Shortly after the last impulse of the series, relay 107 will restore. Parallel circuits are closed from ground, armatures 147, 123, 129, and 142, shaft springs 120, armature 133, off-normal contacts 117, through release magnet 113 to battery, and by way of contacts 40 controlled by armature 132, through the winding of relay 105 to battery. Release magnet 113 operates and the switch wipers are restored to normal position in the usual way. Relay 105 upon operating closes a locking circuit for itself at armature 132 to ground at armature 149. By actuating its armature 133, relay 105 disconnects the shaft springs from the circuit, so that the subsequent operation of the wipers of the fourth level will not affect the release of the switch. Relays 101, 103, 106, and 108 remain operated during the release of the switch.

55 The calling subscriber now dials the second digit of the number which is also assumed to be the digit 4, and relay 101 responds as in the previous instance. The off-normal springs again operate on the first step and close the various circuits previously described. Relay 107 and magnet 112 operate as previously, stepping the wipers to the fourth level. Shaft springs 120 again operate but are without effect at this time, since relay 105 is locked up, and has opened the release circuit at armature 133. Shortly 60 after the last impulse of the series, relay 107

releases and closes a circuit from ground, armatures 147, 123, 129, and 142, off-normal contacts 118, armature 157, interrupter contacts 177, through the rotary magnet 111, to battery. Magnet 111 operates and steps the wipers in on to the first set of contacts in the fourth level. Interrupter springs 177 operate near the end of the stroke of the magnet and open the circuit of the magnet which restores.

70 Assuming that the first trunk of the selected group is busy, the test contact engaged by wiper 161 will be grounded. The test circuit may be traced from wiper 161, upper winding of relay 110, armatures 137 and 149, to ground. The ground encountered by wiper 161 on the busy contact, therefore, shunts the upper winding of relay 110 and consequently the relay does not operate. Rotary magnet 111, however, again closes its interrupter contacts 177 thereby completing the previously traced operating circuit of the magnet. This circuit is maintained as long as the wiper continues to engage a busy contact, the magnet 111 stepping the wipers and opening its own circuit in a buzzer-like manner.

80 Assume that trunk comprising conductors 163—166 is the first idle trunk of the group. This trunk terminates in connector C (Fig. 3), and when idle, is characterized by having battery potential connected to trunk conductor 165. It may be noted that conductor 165 is used only in toll connections and is not shown connected in the banks of selector SR. When the wipers of the selector engage the contacts associated with this trunk, wiper 161 encounters battery potential, relay 110 will operate over the previously traced test circuit and open the circuit of the rotary magnet at armature 157. The wipers of the switch are thereby stopped on the contacts of the idle trunk. Relay 110 closes a locking circuit in series with the rotary magnet at armature 157. The resistance of the lower winding of relay 110, however, is such that magnet 111 does not operate at this time. At armature 156, relay 110 short circuits its upper winding to prevent a possibility of interference from the switch C. At armature 158 the circuit of the vertical magnet is opened and at armatures 155 and 159 a control circuit is extended to the connector by way of wipers 160 and 162. It will be noted that the upper winding of relay 104 is connected in the test circuit in parallel with the upper winding of relay 110 and subsequently directly to test wiper 161 by way of armature 156. The relay, however, is so adjusted that it does not operate in series with either the resistance 313 or the lower winding of relay 302 of connector C, when a connection is extended. The purpose of this relay will be described in later paragraphs.

85 90 95 100 105 110 115 120 125 130 A control loop extending from selector SR

130

to connector C, may now be traced from battery, upper winding of relay 102, upper winding of relay 103, armature 121, normally closed contacts controlled by armature 127, 5 armature 155, wiper 160, trunk conductor 166 to connector switch C, armatures 321 and 341, normally closed contacts controlled by armature 348, upper winding of relay 306, winding of relay 307, armature 326, trunk conductor 10 164, wiper 162, armature 159, normally closed contacts controlled by armature 131, lower winding of relay 103, lower winding of relay 102 to ground. Relay 307, which is the impulsing relay of the connector, operates 15 over the above circuit, but relay 306 does not since the current flow in its upper winding is insufficient to overcome the tension of the armature springs. Further the relay is arranged so that on calls from a local 20 selector, the two windings oppose each other as will be subsequently explained. As previously mentioned, the relay 110 upon operating short circuits its upper winding and connects ground to the release trunk through 25 the low-resistance upper winding of relay 104. This ground extending by way of wiper 161, conductor 165, armature 333, off-normal contacts 315, lower winding of relay 302, resistance 312 to battery, causes the operation 30 of relay 302. Relay 302 locks itself to the release trunk at armature 331, thereby rendering itself independent of off-normal contacts 315. Relay 302 opens a point in the 35 release circuit at armature 329, and at armature 330 connects a ground to local holding conductor 320 the purpose of which will be apparent from the later description. Relay 307 operates as previously mentioned and prepares the impulsing circuit at armature 40 355. The purpose of the parallel battery connection through resistance 313, which is a non-inductive resistance, is to increase the battery flow in the test circuit to insure the quick operation of the switching relay of 45 the selector.

The calling subscriber now proceeds to dial the third digit of the called number which is assumed to be the digit 2. Relay 101 of selector SR responds as in the previous instance 50 and opens the control circuit of relay 307 at armature 121. Relay 307 responds to the impulses and on restoring at each impulse, closes a circuit from ground, armature 330, contacts controlled by armature 355, armatures 325 and 344, thence in two parallel circuits one extending through relay 304 to battery, the other by way of armature 335 55 through vertical magnet 308 to battery. Relay 304 which is a slow acting relay, operates in response to the first impulse and remains operated throughout the series of impulses. Magnet 308 operates in response to 60 each impulse and raises the wipers of the switch opposite the called level, in this case 65 since two impulses were transmitted the wip-

ers are raised opposite the second level of the bank contacts. Relay 304 upon operating closes a point in the trunk circuit at armature 337 shunting the armature 341, and opens a point in the circuit of relay 303 at 70 armature 339. Upon the first vertical step to the wipers, off-normal contacts 315, 316, and 317 are operated, the former opening the circuit of relay 302 which, however, remains locked by way of armature 331 and the release trunk conductor; contacts 316 close a circuit for grounding conductor 320 to be effective after the release of relay 302; and contacts 317 close a point in the circuit of the upper winding of relay 301 and of 80 switch-over relay 303. Shortly after the last impulse of the series, relay 304 restores and closes a circuit from ground, armatures 330 and 355, off-normal contacts 317 closed on the first vertical step, armatures 343 and 339, through the winding of relay 303 to battery. A parallel circuit is closed through the resistance 314, lower winding of relay 306 to battery. Relay 303 operates and locks itself 85 to the release trunk conductor at armature 333 and opens the circuit of relay 302. A point in the circuit of the release magnet is opened at armature 334, and ground by way of off-normal contacts 316 is connected to local holding conductor 320. The impulsing 90 circuit is now switched from vertical magnet 308 to rotary magnet 309 at armature 335. Relay 306 does not operate over the previously traced circuit due to the value of resistance 314. Relay 302 now releases and 95 prepares the ringing and release circuit.

The calling subscriber now dials the final digit of the number, that is the digit 2, and relays 101 and 307 respond as in the previous instance. Relay 307 transmits two impulses 100 to rotary magnet 309 which operates to step the wipers around to the contacts of the called line. Relay 304 again operates and remains operated during the series of impulses. At armature 337 the circuit of relay 307 is 105 maintained and at armature 340 the impulsing circuit is maintained independent of the contacts of relay 305 in order to prevent that relay from interfering with the operation of the switch as the wipers pass over busy contacts. Test relay 305 is connected to test wiper 357 at armature 338. It will be assumed that the called line is the one comprising the conductors 359—361 terminating in 110 sub-station T2. If the called line is busy there will be a ground on the test contact engaged by wiper 357. Relay 305 operates from this ground, and prepares a locking circuit 115 for itself at armature 342. A point in the circuit of relay 307 is opened at armature 341 and points in the circuit of the upper winding of relay 301 are opened at armatures 343 and 345. The impulsing circuit is opened at armature 344, and the busy tone is connected 120 up at armature 347. Shortly after the last 125

impulse of the series, relay 304 releases and opens the circuit of relay 307 at armature 337 and also the impulsing circuit at armature 340. Relay 305 is disconnected from the test 5 wiper and now remains locked up by way of contacts controlled by armature 338, armatures 342, 323, and 334, and off-normal contacts 316 to ground. Relay 307 releases but is without effect at this time.

10 Returning now to selector SR, the opening of the control loop at the connector causes relay 103 to release and open the holding circuit of relay 106 at armature 126. Relay 106 releases and switches the selector over from 15 operating to talking position by switching the talking circuit from wiper 160 through to condenser 178 at armature 135. Relay 104 is shunted out at armature 137 to prevent the subsequent operation of this relay. The busy 20 tone from the connector is now transmitted to the calling subscriber by way of condenser 179 and the lower trunk conductor. The calling subscriber is thereby informed that the called line is engaged and the subscriber is 25 expected to hang up and release the connection.

In case the called line is idle when the 30 wipers of the connector are operated into engagement with the contacts of the line, wiper 357 will not encounter ground, consequently, relay 305 does not operate. When relay 304 releases shortly after the last impulse of the series, relay 301 operates over a circuit from ground, off-normal contacts 316, armatures 334 and 355, off-normal contacts 317, armature 348, upper winding of relay 301, armatures 345, 354, and 338, wiper 357, trunk conductor 360 through the cut-off relay and magnet of the associated line switch corresponding 40 respectively to relay 4 and magnet 6 of line switch LS, to battery. Relay 301 closes a locking circuit for its lower winding at armature 324 in series with vertical magnet 308. Magnet 308, however, does not operate 45 due to the high resistance of relay 301. The ringing circuit is closed through to the called line at armatures 320 and 327 and at armature 321 a ring back circuit for the calling line is closed by way of condenser 319. The control 50 circuit of relay 307 is opened at armatures 321 and 326 and relay 307 restores. Ground from armature 350 is connected directly to the test wiper 357 by way of armature 322 to mark the line locally busy. Relay 301 by 55 operating its armature 325 also prepares a locking circuit for the ring cut-off relay 302. At the selector SR, the switch-over operation takes place as was previously explained when a busy line was connected.

60 The connector now sends out interrupted ringing current over the called line from grounded generator Gen, upper winding of relay 302, armatures 328 and 320, wiper 356, line conductor 359, through the bells at the 65 called sub-station T2, line conductor 361, wiper 358, armatures 327 and 332, to battery. The ringing current is interrupted in the usual way by interrupter INT in order to ring the bell of the called sub-station intermittently. When the called subscriber answers 70 by lifting the receiver at the called sub-station, a direct current path is closed for the upper winding of relay 302 and that relay operates in a well known manner. The ringing circuit is opened at armatures 328 and 332 75 and the talking circuit is completed at those armatures. A point in the release circuit is opened at armature 329 and ground is again connected to local holding conductor 320 at armature 330. Relay 302 also closes a 80 locking circuit for itself which may be traced from ground at armature 330 or off-normal contact 316, conductor 320, contacts controlled by armature 355, (relay 307 having restored) armatures 325 and 331, lower winding of relay 302, resistance 312 to battery. In the selector, relay 103 now operates over the called line loop, the previously traced control circuit for relay 307 having been extended by way of the wipers through to the called line. 85 The two subscribers may now talk, battery for the calling subscriber being supplied through line relay 101, and for the called subscriber through relay 103. The calling and called loops are inductively connected 90 through the condensers 178 and 179.

95 Relay 103 as previously mentioned operates when the called subscriber answers. A circuit is closed from ground by way of armatures 126, 139, and 143 through relay 109 100 to battery. Relay 109 operates and locks to ground at armature 149 by way of armature 153. Relay 109 remains operated during the conversation and closes a point in the talking circuit at armature 150, opens a point in the release circuit at armature 151, and prepares the metering circuit at that armature.

105 When the subscribers finish talking, the receivers at both the calling and the called sub-stations will be restored. When the called 110 party hangs up, the circuit of relay 103, which has been feeding the talking battery to the called party, will be opened and that relay will restore. The calling party upon hanging up opens the circuit of line relay 101 and that relay will restore. A circuit may now be traced from ground, armature 148, contacts controlled by armature 122, through relay 107 to battery. Relay 107 operates, and at armature 142 connects ground 115 to the release trunk by way of armatures 129 and 123, to hold up the cut-off relay 4 of line switch LS and to maintain the holding circuit for switching relay 110 of the selector. The circuit of relay 107 will be maintained 120 a short time after relay 101 releases due to the slow-releasing characteristic of relay 108. Relay 107 is rendered slow-to-release at this time by the short circuit of its lower winding through armatures 138 and 158 and in- 125

130

terrupter contacts 176. Shortly after the release of relay 101, relay 108 will fall back and close the metering circuit which may be traced from ground, meter 7 associated with line switch LS, armature 9, wiper 15, metering conductor, armatures 151, 145, 125, and 128, off-normal contacts 117, through the winding of magnet 113, to battery. Meter 7 operates over the above circuits and registers the call; the magnet 113, however, does not operate due to the relatively high resistance of the meter relay. Relay 107 remains operated for a time after relay 108 falls back and maintains the holding ground on the release trunk. The release of relay 108 also opens the circuit of relay 109 which being slow acting, maintains its armatures actuated for a short time after its circuit is opened, to effect the just described metering function. After a slight delay, relay 109 restores and closes the release circuit at armature 151, opening the metering circuit at the same time. Release magnet 113 operates to restore the switch wipers to normal position, and at contacts 180, closes a holding circuit for relay 107 to keep that relay operated until the connector has reached the normal position. When the wipers return to the normal position, the off-normal contacts are again operated and the circuit of the release magnet is opened at off-normal contacts 117. Release magnet then restores, opens the circuit of relay 107 which likewise restores its armatures, and removes ground from the release trunk thereby permitting the switching relay 4 of the line switch and switching relay 110 of the selector to restore. The release of relay 108 removes the holding ground from test wiper 161 and release trunk conductor 165, thereby permitting relay 303 of connector C to restore. Relay 303 disconnects the lower winding of relay 301 from magnet 308 and connects it instead to the upper talking conductor of the connector at armature 336 and contacts controlled thereby. If the called subscriber has hung up, relay 301 releases after a short interval and opens the holding circuit of relay 302 at armature 325. Relay 302 releases and at armature 329 completes a circuit for release magnet 310 which restores the switch wipers to normal position in the usual way. The switches are thus all restored to their normal positions and are available for another call.

In case the called subscriber fails to hang up after a call, the various switches except connector C release as above described. After the release of relay 303 which occurs in response to the removal of ground from conductor 165, relay 301, it will be recalled, is connected to the upper talking conductor of the connector. Since it is assumed that the called party has not hung up, there will be a circuit for relay 301 extending from ground,

lower winding of the relay, armature 324, contacts controlled by armature 336, armatures 328 and 320, wiper 356, called line loop, wiper 358, armatures 327, 332, 326, 336, winding of magnet 308, to battery. Relay 301 will remain operated over this circuit until the called subscriber hangs up and will, of course, maintain the holding circuit of relay 302. Ground will be applied to conductor 165 by way of armature 330, contacts controlled by armature 355, and armatures 325 and 333 to mark the connector busy in the banks of the selectors. Upon the called party hanging up, the connection will release as previously described.

Revertive call from sub-station T to extension sub-station T1

As previously explained, T and T1 are two sub-stations on the same subscriber's line, T1 being what is ordinarily known as an extension telephone. Both sub-stations are equipped with the usual calling devices and ringers. Assuming that the subscriber at sub-station T desires to talk with the subscriber at sub-station T1, the subscriber at sub-station T will remove the receiver from the hook and line switch LS will operate in the manner previously described to extend the calling loop to a selector such as selector SR. A particular level in the banks of the selectors is set aside for revertive ringing, for example, the ninth level. A calling subscriber, therefore, dials only the digit 9 to complete the call.

When the call is extended to a selector which will be assumed to be the selector SR, relays 101, 103, 106, and 108 operate as previously described. Relay 101 responds to the interruptions from the calling device at sub-station T and transmits a series of impulses, in this case 9 impulses, to vertical magnet 112 which operates and sets the wipers opposite the ninth level exactly as in the previous connection. Relay 107 operates during the series of impulses as in the previous connection. Shortly after the last impulse of the series, relay 107 releases and completes the usual rotary circuit. The wipers of the selector are then automatically advanced step by step until an idle trunk is reached. Assuming that the first idle trunk is the one comprising conductors 167-169, the wipers of the selector advance to the contacts associated with this line. Switching relay 110 of the selector operates over the usual testing circuit of the selector and by way of wiper 161, trunk conductor 168, contacts controlled by armature 226 of relay group RC, resistance 209, relay 207, to battery. Relay 207 of the relay group does not operate in this circuit, due to the value of resistance 209. Relay 110 upon operating extends the control loop of selector SR through to relay group RC, a circuit extending from

battery, upper windings of relays 102 and 103, armature 121, contacts controlled by armature 127, armature 155, wiper 160, trunk conductor 169, armature 220, upper winding of relay 201, armature 228, lower winding of relay 201, armature 222, trunk conductor 167, wiper 162, armature 159, contacts controlled by armature 131, lower windings of relays 103 and 102, to ground. Relays 103 and 106, which were operated in a local circuit previous to the switch through of the selector, are now held up over the loop circuit through relay group RC. Relay 110 short circuits its upper winding at armature 156 and relay 106 removes the short circuit from the upper winding of relay 104 as in the previous connection. Relay 201 of the relay group now operates over the control loop, closes a circuit for relay 202 at armature 212, prepares a holding circuit for relay 203 at armature 211, and at armature 210 short circuits resistance 209 in the release trunk circuit. The increased current flow in this circuit now causes relay 104 of selector SR and relay 207 of relay group RC to operate in series. Relay 104 upon operating connects the calling loop straight through to wipers 160 and 162 by way of armatures 127 and 131, and opens the circuit of impulsing relay 101 at those armatures. Relay 104 opens a point in the release circuit at armature 128, connects the upper and lower windings of relay 110 in series at armature 129, and at armature 130 closes a locking circuit for its own lower winding in parallel with the holding circuit of relay 110. Relay 101 now restores followed by the restoration of relays 103, 106 and 108. Relay 207 on operating, connects the lower winding of relay 206 to the release trunk by way of armature 230. Relay 206 now operates and relays 110 and 104 are held up over a circuit extending from ground, lower winding of relay 206, armature 230, conductor 168, wiper 161, armatures 156, 129, and 123, lower winding of relay 110, armature 157, interrupter contacts 177, through rotary magnet 111 to battery. The circuit of relay 104 includes armature 130. Relay 206 upon operating closes a locking circuit for itself at armature 227 by way of armature 214 and at armature 226 connects a direct ground to the release trunk to hold up relays 110 and 104 of selector SR over the previously traced circuit. Relay 207 is now disconnected from the release trunk and that relay releases and opens the original energizing circuit of relay 206 of armature 230. Relay 206, however, remains locked up and connects battery and ground, respectively, to the upper and lower winding of relay 201, which is now held operated over the calling loop. Relay 202 on operating as previously mentioned, closed a locking circuit for itself at armature 215 and including armature 218, prepared a cir-

cuit for grounding the release trunk at armature 214, and at armature 216 prepared an operating circuit for relay 204.

The calling subscriber now restores the receiver to the switch hook, opening the calling loop, and relay 201 releases. The original energizing circuit of relay 202 is opened at armature 212, and a circuit is closed to relay 204 which may be traced from ground at armatures 216, 213, and 219, winding of relay 204, to battery. Relay 204 operates and at armatures 220 and 222 closes the ringing circuit, and closes the circuit for relay 205 at armature 221. Relay 205 operates, closes points in the holding circuit of relay 203 at armatures 223 and 224, and at armature 225 completes a locking circuit for itself to ground on the release trunk. Ringing current or ground is now intermittently connected to the calling line over a circuit which extends from grounded generator GEN or ground by way of armature 231 of interrupter relay INT, lower winding of relay 203, armature 220, conductor 169, wiper 160, armatures 155 and 127, upper talking conductor of the selector, wiper 14 of the line switch LS, armature 8, line conductor 2, through the bells and condensers at both sub-stations T and T1, line conductor 3, armature 11, wiper 17, lower talking conductor of the selector, armatures 131 and 159, wiper 162, conductor 167, armature 222, to battery. The bells at both sub-stations will ring intermittently until a receiver is lifted at one sub-station or the other. Assuming that the called party, that is the subscriber at sub-station T1, answers first, a direct current circuit is closed for relay 203 and that relay operates and closes a locking circuit for itself at armature 217 to ground on the release trunk by way of armatures 224 and 226. Relay 203 opens the locking circuit of relay 202 at armature 218, and at armature 219 opens the circuit of relay 204. Relay 204 now restores and opens the ringing circuit at armatures 220 and 222 and again connects relay 201 to the calling loop. Relay 201 operates, closes the circuit of relay 202 before that relay has had time to fall back, and at armature 211 closes an additional locking circuit for relay 203.

The calling subscriber on noting that the ringing has ceased, knows that the called subscriber has answered and, therefore, will again lift his receiver and the conversation may take place. Talking battery for both subscribers is furnished through the winding of relay 201.

When the conversation is finished, both parties will restore their receivers, thus opening the circuit of relay 201 which releases, opens the circuit of relay 202 and the additional locking circuit of relay 203. Relay 202 releases followed by the release of relays 203 and 206 and relay group RC is restored

to normal position. The release of relay 202 removes ground from the release trunk at armature 214 and relays 110 and 104 of selector SR release. Relay 104 upon restoring, 5 closes a point in the circuit of the release magnet, the circuit extending from ground, armatures 151, 145, 125, and 128, off-normal contacts 117, winding of release magnet 113 to battery. The release magnet operates to 10 restore the wipers to normal position, and at contact 180 closes an energizing circuit to relay 107. Relay 107 operates, at armature 142, connects ground to the release trunk to guard the selector against seizure until the 15 wipers have reached normal position. On reaching normal position, the off-normal contacts are operated and the circuit of the release magnet is opened at contact 117. Relay 107 now releases and removes the guarding 20 ground from the release trunk and the apparatus is again in condition for another call.

Call from sub-station T to sub-station T3

25 When the receiver is lifted at sub-station T, line switch LS operates as previously described to extend the calling line to a selector. Assuming that the selector SR is the one taken into use, relays 101, 103, 106, and 30 108 operate as previously described in a local connection. The sub-station T3 is assumed to be in office "B" to which the digit 3 has been assigned as an office code. For purpose of illustration it may be assumed that 35 the directory number of this sub-station is 3322. The calling subscriber now dials the first digit, that is the digit 3, and the wipers of selector SR are raised to the third level exactly as was done in a local call. Shaft 40 springs 120, however, are not operated on this level and, consequently, relay 105 does not operate to release the selector and cancel the first digit. Shortly after the last impulse of the series, relay 107 releases and closes the 45 previously traced rotary and testing circuits by means of which the selector now selects an idle trunk. The trunk selected, for example, may be the one comprising conductors 173-175 terminating in selector ISR at ex- 50 change "A" and in selector ISR1 at exchange "B". It may be noted that signal relays ASR and ASR1 have associated with the trunk at offices "A" and "B", respectively.

The test circuit including the upper winding of relay 110 extends by way of wiper 161, conductor 174, contacts controlled by armature 746, (Fig. 7) through the winding of relay 712, to battery. Relay 110 operates to switch through the control loop, closes its 60 own locking circuit and opens the circuit of the vertical magnet as was described in the previous connection. Relay 712 of the alarm signal relays also operates and closes a circuit for relay 711 at armature 750. Relay 65 711 operates and closes an alternate holding

circuit for relay 712 by way of armatures 746 and 749. A circuit is also closed from ground, armature 748, conductor 174', thence through armature 625, winding of relay 601 of the incoming selector ISR (Fig. 6), to battery. Relay 601 operates and at armatures 621 and 623 disconnects the selector ISR from the trunk. The control loop of selector SR which includes the two windings of relay 103, is now extended by way of wipers 70 160 and 162, trunk conductors 173 and 175, armatures 833 and 835 of incoming selector ISR1 (Fig. 8), through the left-hand windings of the repeating coil R, contacts controlled respectively by armatures 840 and 841, and through the upper windings of relays 802 and 805 in series. Relay 802, which is the impulsive relay, operates in the above traced circuit, but relay 805 does not since the current flow in its upper winding is insufficient to actuate the armatures. Relay 802 upon operating closes a circuit from ground, armature 888, winding of relay 803, thence through relay 810 to battery, and in parallel therewith through vertical magnet 817 to battery by way of armature 878. Relay 803 operates in the circuit but relay 810 and the vertical magnet do not operate due to the high resistance of relay 803. Relay 803 85 upon operating grounds the local holding conductor at armature 837, disconnects cut-off relay 801 at armature 836, and opens a point in the release circuit at 838. The grounding of the local holding conductor completes a circuit for the lower winding of relay 805 in series with resistance 822. Relay 805, however, does not operate at this time due to the value of resistance 822 and due to the fact that the two windings now oppose 90 each other. Impulsive relay 802 upon operating also closes a circuit from battery through the lower windings of relays 808 and 807, armatures 889, 891, and 844, lower right-hand winding of repeating coil R, contacts controlled by armature 879, resistance 890, to 95 ground. Relay 807 operates over this circuit, but relay 808 does not operate due to the resistance 890.

The subscriber now dials the second digit of the called number, in this case the digit 3, 100 and relay 101 responds to the interruption of the calling loop as in the previously described connection. The circuit of the control loop is intermittently opened at armature 121, and relay 802 responds to these interruptions by retracting its armatures three times. Each time relay 802 drops back, a circuit is closed from ground, armature 837, contacts controlled by armature 888, through the winding of relay 810 to battery, and in 105 parallel therewith by way of armature 878, through vertical magnet 817, to battery. Magnet 817 responds to these impulses and raises the wipers of the switch three steps 110 to the third level. Relay 810 also operates 115

in response to the impulses and due to its slow releasing characteristics remains operated throughout the series of impulses. This slow releasing action of relay 810 is due to its series connection with relay 803 when relay 802 is in operated condition. Relay 803 also remains operated during the impulsive as its winding is short circuited at contacts controlled by armature 888, which renders the relay slow acting. Each time relay 802 drops back to transmit an impulse, a holding circuit for relay 807 is closed which may be traced from battery, lower windings of relays 808 and 807, contacts controlled by armature 889, and resistance 821, armature 843, to ground on the local holding conductor at armature 837. Relay 808 is prevented from operating at this time by resistance 821. After the last impulse in the series, relay 810 releases, closes a circuit from ground on the local holding conductor, off-normal contacts 827 which closed on the first vertical step of the wipers, release magnet contact 831, armatures 858 and 877, interrupter springs 832, through the winding of rotary magnet 818, to battery. Magnet 818 operates and steps the wipers in on the contacts of the first trunk in the selected level and near the end of its stroke opens its own circuit at interrupter contacts 832. The magnet then releases and again closes its circuit at interrupter contacts 832 and unless the rotary circuit has been opened at some other point, another rotary step is imparted to the wipers. This action takes place until an idle trunk is encountered which may be assumed to be the trunk comprising conductors 931-934 terminating in connector C1, Fig. 9.

The idle trunk is marked by the presence of battery potential on the test contact by way of the ring cut-off relay of the connector C1 (corresponding to relay 302 of connector C). Relay 815 now operates from the battery encountered by wiper 885, armature 852, upper winding of relay 815, and ground on the local holding conductor. Relay 815 upon operating switches the control loop including the lower winding of relay 807 through to the line relay of the connector C1. The line relay of connector C1 corresponds to the relay 807 of connector C previously described. The control circuit extends from battery, lower windings of relays 808 and 807 in series, armatures 889, 891, and 844, lower right-hand winding of repeating coil R, armatures 879 and 882, wiper 886, trunk conductor 932, through the line relay of connector C1 (corresponding to relay 307 of connector C), trunk conductor 934, wiper 883, armatures 880, 875, and 867, upper right-hand winding of repeating coil R, armature 842, to ground. Relay 807 remains operated now over the above traced loop circuit. Relay 808 does not operate at this time due to the resistance of the loop circuit. It will be noted that the

two right-hand windings of repeating coil R are connected by way of armature 854 and condenser 893.

The subscriber now dials the last two digits of the called number and relays 101 and 802 respond as in the previous instance. Relay 802 interrupts the control loop extending to connector C1 at armature 889 and completes the holding circuit for relay 807 during impulsive as previously explained. Connector C1 responds to the two digits in the same manner as explained for connector C and advances wipers 356'-358' into engagement with the contacts of the called line, for example, the line comprising conductors 2', 3', and 20'. Relay 810 again operates during each series of impulses and at armature 854 opens a connection between the right-hand winding of the repeating coil R.

If the called line is busy, wiper 357' encounters a grounded contact and the busy relay of the connector will operate to open the control loop and to connect the busy tone to the trunk. When the control loop is opened, relay 807 deenergizes and at armature 851 closes a circuit for relay 804. Relay 804 operates and at armature 843 locks itself to the local holding conductor. The windings of relays 802 and 805 are now disconnected from the control loop extending from selector SR, and relays 806 and 809 are connected, respectively, to the trunk conductors 173 and 175. Relay 806 now operates in series with the lower windings of relays 103 and 102 of selector SR, but due to the very high resistance of relay 806, relay 103 retracts its armatures. Relay 806 also closes a holding circuit for impulsive relay 802, from ground, armature 849, lower winding of relay 802, to battery. The busy tone from the connector is now induced on the trunk line by way of the repeating coil R, and is audible to the calling subscriber who is thus informed that the calling line is engaged. The calling subscriber is expected to hang up and release the connection.

In case the line connected with is idle, connector C1 switches through in the usual way, and cut-off relay 4' of line switch LS1 associated with the called line operates, disconnecting battery and ground from the line. The connector switches through and opens the control loop as previously explained in the operation of connector C. Relay 807 releases and relay 804 operates exactly as described for a call to a busy line. The release of relay 103 and selector SR initiates the switch-over operation in that selector as previously described, that is the switch is changed over from operating to talking condition by the release of relay 106. The connector signals the called subscriber in the usual way by transmitting ringing current over the line conductors. When the called subscriber answers, the connector cuts off the

ring, and extends the control loop through to the called sub-station as in the previous connection. Relay 807 now operates over the called line loop, a circuit extending from battery, lower windings of relays 808 and 807 in series, armatures 889, 872, and 844, lower right-hand winding of repeating coil R, armatures 879 and 882, wiper 886, trunk conductor 932, upper talking conductor and connector C1, wiper 356', line conductor 2', through the transmitter and receiver at the called sub-station T3, line conductor 3', wiper 358', lower talking conductor of connector C1, trunk conductor 934, wiper 883, armatures 880, 875, and 867, upper right-hand winding of repeating coil R, armatures 868 and 893, through the upper windings of relays 807 and 808 in series, to ground. Relay 807 upon operating, disconnects relay 809 from trunk conductor 175 and connects battery to that conductor by way of armature 850 and resistance 823. Relay 807 also short circuits the high resistance winding of relay 806 by actuating its armature 851. Relay 806 remains operated over its low resistance upper winding, and relay 103 of selector SR operates also. Relay 103 prepares the metering circuit previously described and supplies talking current to the loop extending between the two selectors.

The two subscribers may now converse, talking battery for the calling subscriber being supplied through the windings of relays 101 and 102, and talking battery for the called subscriber being fed through the windings of relays 807 and 808.

At the end of the conversation, the calling and called subscribers hang up their receivers. When the called subscriber hangs up, the operating circuit of relay 807 is opened and that relay restores. The short is removed from the lower winding of relay 806 and relay 103 of selector SR restores. When the calling subscriber hangs up the receiver, relay 101 restores followed by relays 108, 109, 110, and 106 as in a local connection. Relay 109 closes the metering circuit in the usual way, relay 107 provides the usual holding ground to prevent the release of line switch LS until the metering operation has taken place, and subsequently to guard the selector from seizure until the wipers have been restored to normal position. Relay 101 on releasing opens the circuit of relay 806 which releases and opens the holding circuit of relay 802. Relay 802 releases followed by relays 803, 804, and 815. A circuit for the release magnet is now closed extending from ground, armature 838, off-normal contacts 826, winding of release magnet 819, to battery. Release magnet 819 operates to restore the wipers to normal position and at contact 831 opens the circuit of the rotary magnet which prevents that magnet from interfering with the release operation after relay

815 restores. When the wipers of the switch ISR1 reach the normal position, the release magnet circuit is opened at off-normal contacts 826. Connector C1 and line switch LS1 restore in the usual way following the opening of the control loop at selector ISR1. All of the switches involved in the connection have now returned to normal position, and are in readiness to respond to another call.

Call from sub-station T3 to sub-station T4

A local call in the "B" office, for example, a call from sub-station T3 to sub-station T4 is completed in exactly the same manner as the previously described local call in the "A" office. When the receiver is lifted at sub-station T3 line switch LS1 operates in the usual way to extend the connection to an idle selector such as the selector SR1. Selector SR1 is exactly the same as selector SR (Fig. 1) except that the shaft springs are adjusted to operate when the wipers are raised to the third level which corresponds to the office digit in this case. The calling subscriber, therefore, dials the digit 3, and selector SR1 responds and then releases. The second digit, which may also be the digit 3, again operates the selector to the third level of the bank, whereon the selector automatically cuts in and hunts for an idle trunk. The trunk selected may be the one comprising conductors 931-934 terminating in connector C1. The connector C1 is identical with connector C (Fig. 3), as previously explained. Connector C1 responds to the last two digits of the called number and advances its wipers 356'-358' into engagement with the contacts of the called line, for example, the line comprising conductors 359'-361'. The line switch associated with that line, functions as previously described for line switch LS1 and connector C1 signals the called party in the usual way. The switching operation of selector S1 takes place when an idle or busy line is encountered, and this selector supplies talking battery to both subscribers. At the end of the conversation, the metering operation and release take place exactly as described for selector SR, and connector C.

Call from sub-station T to toll recording operator

When the calling subscriber at sub-station T lifts the receiver to initiate the call, line switch LS operates in the well known manner to extend the calling line to a selector, for example, the selector SR. In order that the code numbers dialled to call the operator may be the same throughout the system, a two digit code, in this case the code number 40, is assigned for this service. The subscriber now dials the digit 4 and selector SR responds exactly the same as for a local call, the wipers being stepped to the fourth level

and then released. In response to the second digit, the wipers of the selector are stepped to the tenth level and the automatic cut-in and hunting operations take place as explained in previous connections. Assume that the trunk comprising conductors 170—172 is the first idle trunk encountered by the selector. The test circuit including the upper winding of relay 110 of selector SR now extends by way of wiper 161, trunk conductor 171, to the toll transmission selector, Fig. 5, armature 528, through the winding of relay 501 to battery. Switching relay 110 of the selector and relay 501 of the toll transmission selector operate in series over the test circuit. Relay 501 disconnects transmission selector TTS from the trunk at armatures 527 and 522. Relay 110 upon operating switches the control loop through as previously described, and a circuit may be traced from battery, through the upper windings of relays 102 and 103, armature 121, contacts controlled by armature 127, armature 155, wiper 160, trunk conductor 172, thence to the trunk relay group RCT (Fig. 4), contacts controlled by armature 418, lower right-hand winding of repeating coil R1, armature 408, through the winding of relay 403, to battery. The resistance of relay 403 is very high and relay 103 does not remain operated when connected in series with that relay. Relay 403, however, operates and closes a circuit for relay 404 at armature 410. Relay 404 operates, prepares a circuit for the lower winding of relay 405 at armature 412, and at armature 411 connects ground to the line signal lamp L1 by way of armature 414. Relay 103 of selector SR releases and opens the circuit of relay 106, whereon the selector SR switches over from operating condition to talking condition in the same manner as when a call is extended to an idle local line. Lamp L1 lights to inform the operator that a call is awaiting attention.

On noting the lighted condition of lamp L1, the operator inserts the plug P of an answering cord AC into jack J. Battery on the sleeve of the answering plug by way of the sleeve of jack J, contacts controlled by armature 409, and armature 412, operates relay 405 over its lower winding. Relay 405 opens the circuit of lamp L1 at armature 414, and at armature 415 closes a locking circuit for its lower winding independent of armature 412. The resistance of relay 405 is such that the supervisory lamp S in the answering cord will not light in series therewith. The operator may now actuate the talking key K1 of the answering cord circuit and converse with the calling subscriber. After ascertaining the wants of the calling subscriber, the operator informs the subscriber that the call will be completed and that he will be called again at that time, at the same time requesting the subscriber to hang up. The operator

will then proceed to complete the toll call over the regular toll line and will eventually call back the subscriber by way of the toll transmission selector as will be described in later paragraphs.

When the calling party hangs up, selector SR and line switch LS release as in the previous case, except that since relay 103 of selector SR was not reoperated when the operator answered the call, the metering relay 109 was not operated and the release takes place without any registration of the meter at the calling line. Relay 101, of selector SR, opens the circuit over which relay 403 was held operated, and that relay restores. The circuit of relay 404 is opened, and that relay also restores. Ground by way of resistance 419 and armature 412 is now connected to the sleeve of the trunk circuit in parallel with ground through the lower winding of relay 405 by way of armature 415. The value of resistance 419 is such that the supervisory lamp S of the cord circuit will operate, but relay 405 is not shunted out, and consequently maintains the circuit of lamp L1 open. The operator noting the lighted condition of the supervisory lamp S will withdraw the plug P from the jack, thereby opening the circuit of relay 405 which will restore. All equipment involved in the connection is now returned to normal and is in readiness to receive another call.

Call from sub-station T3 to the toll recording operator

The subscriber at sub-station T3 may also call the toll recording operator by dialling the code number 40. When the receiver is lifted at sub-station T3, line switch LS1 operates in the well known manner to extend the calling line to a local selector such as the selector SR1. The subscriber then dials the first digit, that is the digit 4, and selector SR1 raises its wipers to the fourth level and automatically hunts for an idle trunk, for example, the trunk comprising the conductors 173, 174", and 175 extending to exchange "A" and terminating in selector ISR at that exchange. The switching relay of the selector operates in series with relay 907 of alarm signal relay group ASR1, and switches through the control loop in the usual manner. Relay 907 operates, completes a circuit for relay 906 at armature 926, a holding circuit for itself at armature 925, and at armature 927 connects ground to release trunk conductor 174" to operate relay 801 of incoming selector ISR1 which is associated with the seize trunk in the "B" office. Relay 801 operates and disconnects the selector from the trunk at armatures 833 and 835. The parallel battery connection through resistance 820 is of no utility in this instance but is required for those trunks which are not equipped for alarm signal extension.

- As previously explained, the circuit of selector SR1 is identical with that of selector SR. The control loop of the selector is now extended by way of wipers 160' and 162', trunk conductors 173 and 175 to incoming selector ISR (Fig. 6), thence by way of armatures 621 and 623, contacts controlled by armature 635, off-normal contacts 615, through the upper winding of relay 604. The lower winding of relay 604, which is of very high resistance, is short circuited by the off-normal contact 615. Relay 604 operates over the above traced circuit and closes a circuit for the lower winding of impulsing relay 603 at armature 631. Relay 603 closes a circuit for relay 602 in series with vertical magnet 610 and relay 605. Relay 602 operates, disconnects cut-off relay 601 from release trunk conductor 174', prepares the impulsing circuit at armature 626, grounds the common holding conductor at armature 627, and opens a point in the release circuit at armature 628. Relay 603 also closes a circuit from battery, through the upper windings of relays 608 and 607 in series, armature 629, contacts controlled by armature 640, through the lower winding of relay 606 to ground. Relays 607 and 606 now operate, but relay 608 does not due to the resistance in the circuit. Relay 606 locks itself to ground by way of its upper winding and armatures 650 and 637. At armature 635 it connects the upper winding of relay 603 in the control loop in place of the upper winding of relay 604. Relay 604 now releases and opens the original energizing circuit of relay 603 at armature 631. Relay 603, however, is now held operated over the control loop. The subscriber now dials the second digit, that is the digit 0, and the line relay of the selector SR1 responds the usual way and interrupts the control loop ten times. Impulsing relay 603 which is controlled over this loop, responds to the impulses and transmits current impulses to the vertical magnet over a circuit extending from ground, armature 626, contacts controlled by armature 630, armature 643, vertical magnet 610 to battery. Relay 605 operates in parallel with the vertical magnet, and due to its slow releasing characteristic remains operated throughout the series of impulses. The wipers of the selector are advanced ten steps to the tenth level of bank contacts. Shortly after the last impulse of the series, relay 605 restores and closes a circuit from ground by way of armature 627, armature 632, off-normal contacts 616 which closed on the first vertical step of the wipers, armature 642, interrupter contacts 645, through the winding of rotary magnet 611 to battery. Magnet 611 responds and steps the wipers in on the first set of bank contacts and opens its own circuit at contacts 645. The hunting operation then takes place exactly as described in previous connections, magnet 611 alternately operating and releasing and advancing the wipers until an idle trunk is connected with. Assuming that the first idle trunk is the one comprising conductors 170-172, when the wipers engage the contacts associated with this trunk, a circuit is closed from battery through resistance 519 and armature 533, and in parallel therewith from battery, relay 501, armature 528, trunk conductor 171, wiper 647, armature 639, upper winding of relay 609 to ground at armature 627. Switching relay 609 operates and switches through the control loop of selector ISR in the usual manner. Cut-off relay 501 of toll transmission selector TTS also operates and disconnects that switch from the trunk. The purpose of the battery feed through resistance 519 in this instance is to insure the quick operation of relay 609 as was previously explained. Relay 609 switches through the control loop at armatures 640 and 644, at armature 641 short circuits its upper winding, closes a locking circuit for itself in series with the rotary magnet at armature 642, and at armature 643 it opens the point of the circuit of vertical magnet 610. The control loop in selector ISR is similar to that of previously described selectors. In this case, since the call is to an operator's position, a circuit extends from battery, upper windings of relays 608 and 607 in series, armatures 629 and 640, wiper 646, conductor 172, thence to trunk relay group RCT (Fig. 4), contacts controlled by armature 418, lower right-hand winding of repeating coil R1, armature 408, through the winding of relay 403 to ground. Relay 403 operates as previously described on a call from sub-station T2 and signals the operator. Due to the high resistance of relay 403, relay 607 retracts its armatures and opens the holding circuit of relay 606, which also restores. Relay 606 by retracting its armature 635 now connects the high and low resistance winding of relay 604 in series across the control loop. Relay 604 operates and closes the holding circuit for relay 603 at armature 631. Due to the high resistance of the two windings of relay 604, the switch-over relay and battery feed relay of selector SR1 restore and switch over that selector from operating position to talking position.
- The operator answers the call as described in the previous connection, and determines the wants of the calling subscriber. Since the answering of the call does not cause the operation of battery feed relay 607 of selector ISR, the corresponding relay of the selector SR1 does not operate to prepare the metering circuit. When the calling subscriber now hangs up, selector SR1 and line switch LS1 release in the usual way except that there is no metering operation. Relay 907 of alarm signal relay group ASR1 and

cut-off relay 801 of selector ISR1 also release. When the holding loop of relay 604 is opened that relay restores and opens the holding circuit of relay 603 which also releases. The circuit of relay 602 is opened, that relay releases, removes ground from the local holding trunk to open the circuit of relay 609, and closes a point in the circuit of release magnet 612. Release magnet 612 operates to restore the wipers to normal. The circuit of the magnet is opened at off-normal contacts 614 which open when the wipers reach normal position. At the toll board, relay 403 drops back and opens the circuit of relay 404 which also drops back and closes the previously described supervisory circuit to give the operator "disconnect" supervision. The operator then withdraws the plug of the answering cord from the jack and all apparatus is returned to normal condition.

Call from sub-station T3 to sub-station T2

A subscriber at sub-station T3 in office "B" when calling a subscriber at sub-station T2 in office "A", dials the first two digits and operates selectors SR1 and ISR in exactly the same manner as on a call to the toll recording operator. It will be recalled that the directory number of sub-station T2 is the number 4422. Selector ISR is, therefore, operated to the fourth level where the hunting operation takes place and an idle trunk, for example, the trunk comprising conductors 163—166, is connected with in the usual way. It will also be recalled that the operation of the switching relay 609 of selector SR connected through the control loop of that selector, the circuit of which may be traced from battery through the upper windings of relays 608 and 607 in series, armatures 629 and 640, wiper 646, conductor 166, armatures 321 and 341, contacts controlled by armature 348, upper winding of relay 306, winding of relay 307, armature 326, conductor 164, wiper 648, armature 644, lower winding of relays 607 and 608 in series, to ground. Line relay 307 of connector C operates as in the previously described local connection, and prepares the impulsing circuit. The subscriber at the calling sub-station now dials the last two digits of the number. The line relay of selector SR1 interrupts the control loop extending to selector ISR and impulse relay 603 of that selector responds. The control loop extending from selector ISR to connector C is likewise interrupted at armature 629 and the line relay of this connector responds to transmit impulses to the stepping magnets of the switch. As relay 603 drops back in response to each impulse, a holding circuit is closed which may be traced from ground, resistance 617, armature 624, contacts controlled by armature 629, through the upper windings of relays 607 and 608 to battery. This circuit maintains relay 607 in

operated position and relay 607 in turn maintains the holding circuit for switch-over relay 606. The wipers of connector C are advanced in the engagement with the contacts of the called line. The control loop is opened when the connector engages the line, whether or not the line is idle, and the circuit of relay 607 is opened. Relay 607 restores and opens the circuit of relay 606 which also restores and switches over the selector ISR from operating to talking position. It will be recalled that the release of relay 606 connected the two windings of relay 604 in series across the control trunk extending from selector SR1, and that the battery feed and switch-over relays of that selector deenergized due to the increased resistance of the loop. The selector SR1, therefore, switches over from operating to talking position. If the called line is busy, the connector returns the busy tone to the calling subscriber in the usual way, and the subscriber is expected to hang up and release the switches. If the called line is idle, the connector signals in the usual way and extends the control loop from selector ISR to the called sub-station. When the called subscriber answers, an operating loop is closed for relay 607 and that relay responds and short circuits the high resistance lower winding of relay 604 at armature 636. The increased current flow through relay 604 now permits the battery feed relay (corresponding to relay 103 of selector SR) of selector SR1 to operate and initiate the operation of metering relay of the selector. Talking battery is fed to the calling subscriber and to the interoffice trunk by selector SR1 in the same manner as the previously described selector SR furnished talking battery to a calling and called subscriber. Talking battery for the called party is supplied through relay 607 of incoming selector ISR.

When the calling and called subscribers hang up their receivers, the switches involved in the connection all restore to normal as has been previously described, the local selector SR1 transmitting a metering impulse to the calling line before the line switch is permitted to restore.

Toll call to sub-station T2

All toll calls in systems of the type shown herein are set up by a toll operator over a toll switch train including for example, the toll trunk extending from trunk relay group RCT to a toll transmission selector such as the selector TTS (Fig. 5) together with combination toll and local switches in the automatic exchanges. By way of illustration, a call from the operator's position, by way of the above mentioned toll trunk and toll transmission selector, to a subscriber at sub-station T2 (Fig. 3) will be described.

The operator on receiving a call over a toll

line, or after having completed such a call over a toll line, will connect that toll line with the trunk selected, such as the trunk comprising conductors 170 and 172, by means 5 of the usual cord circuit (not shown) and jack J of the trunk relay group. The operator will then insert the plug P1 of a dialling board, such as the cord DC, into jack J1 associated with the trunk. On inserting plug 10 P1 in the jack J1, relay 406 will operate from ground on the sleeve of the plug by way of the sleeve of jack J1. Relay 406 when operated at armatures 416 and 418, disconnects the trunk conductors from the relay group 15 and extends them by way of the jack and plug through the loop including the calling device of the dialling cord DC. At armature 417, relay 406 closes a circuit for the upper winding of relay 402 and that relay operates and locks to battery on the sleeve of 20 the regular toll cord, which is assumed to be now connected to the trunk by way of jack J.

Impulse relay 503 of toll transmission selector TTS now operates over a circuit from 25 battery, lower winding of relay 503, contacts controlled by armature 547, lower left-hand winding of repeating coil R2, armature 522, trunk conductor 170, armature 416, tip of jack J1, tip of plug P1, through the normally 30 closed upper right-hand contacts of key K2, impedance 431, normally closed lower left and right hand contacts of key K2, through the impulse contacts of the calling device CD, ring of plug P1, ring of jack J1, armature 418, trunk conductor 172, armature 527, upper left-hand winding of repeating coil R2, 35 normally closed contacts controlled by armature 542, through the upper winding of relay 503 to ground. Relay 503 on operating closes a circuit from ground, armature 534, winding of relay 502, thence in two parallel circuits, through the windings of relay 509 to 40 battery, and, by way of armature 577, through the winding of vertical magnet 516 to battery. Relay 503 also closes a circuit from battery, lower winding of relay 511, armatures 535, 554, and 546, lower right-hand winding of repeating coil R2, contacts controlled by armature 578 to ground. Relay 45 502 operates over the above traced circuit, but due to the relatively high resistance of this relay, magnet 516 and relay 509 do not operate. Relay 502 when operated disconnects cut-off relay 501 from test conductor 171 at 50 armature 528 to mark the trunk busy to selectors in the automatic exchange; connects ground to common holding conductor 585 at armature 529; prepares the impulsive circuit and its own holding circuit at armature 530; prepares a holding circuit for relay 511 at armature 531; and at armature 532, opens a point in the circuit of the release magnet. Relay 511 operates over the circuit above traced and at armature 556 opens a point in 55 the circuit of switchover relay 508.

The operator will now proceed to dial the number of the called line. The selection of the trunk such as the one comprising conductors 170 and 172, is equivalent to the selection of the exchange in which the subscriber is located, and it will, therefore, be necessary to dial only the last three digits of the subscriber's directory number when the subscriber is located in the exchange "A" as in the present instance. The directory number of sub-station T2 is assumed to be 4422, and the toll operator will, therefore, dial the digits 4-2-2. The operator now turns the calling device to the digit 4 and the off-normal springs of the calling device close as the dial is turned off-normal to short circuit impedance 431. As the calling device returns to normal, the previously traced operating circuit of relay 503 is interrupted four times at the impulse contacts. Relay 503 responds in the usual way by dropping back at each interruption of its circuit and reoperating as the circuit is closed. Each time relay 503 drops back, a circuit is closed from ground, armature 530, contacts controlled by armature 534, through the windings of relay 509 to battery, and in parallel therewith by way of armature 577, through the windings of vertical magnets 516 to battery. Magnet 516 operates in response to each impulse and raises the wipers of the switch opposite the fourth level. Relay 509, which is slow acting due to its series connection with relay 502 during the operated condition of relay 503, responds to the first impulses of the series and remains operated throughout the series. Relay 502 is short circuited each time relay 503 drops back, and being slow to release, maintains its armature actuated throughout each series of impulses. As relay 503 responds to each impulse, a holding circuit for the lower winding of relay 511 is closed by way of contacts controlled by armature 535 and armature 531. Relay 511, therefore, remains in operated position during the impulsive. Relay 509 on operating closes a circuit for relay 512 at armature 551, and at armature 552 opens a point in the circuit of rotary magnet. Relay 512 operates and locks to ground on common holding conductor 585 by way of armatures 559 and 545, prepares the busy tone and discriminating test circuits at armatures 557 and 560, and at armature 558 opens a point in the busy-cut-in circuit which will be explained subsequently.

Shortly after the last impulse of the series, relay 509 restores and closes a circuit from ground on common holding conductor 585, off-normal contacts 524, which closed on the first vertical step to wipers, interrupter contacts 536, armatures 552 and 576, interrupter contacts 579, through the winding of magnet 517 to battery. Magnet 517 operates and steps the wipers in on the first set of contacts in the called level and opens its own

circuit at contacts 579. It is obvious that as long as ground is maintained on the conductor leading through interrupter contacts 579, magnet 517 will operate and restore to advance the wipers of the switch one step at a time. This condition obtains as long as the test wiper of the selector encounters a busy trunk. When an idle trunk is reached, for example, the trunk comprising conductors 163-166 terminating in connector C (Fig. 3), a circuit is completed from battery resistance 312, lower winding of relay 302, and in parallel therewith, battery through resistance 313, off-normal contacts 315, normally closed armature 333, trunk conductor 165, test wiper 582, upper winding of relay 515 to ground on common holding conductor 585. Relay 515 operates in series with relay 302. A non-inductive resistance 315 is connected in parallel with relay 302 to increase the current flow in the above circuit and to insure the quick operation of relay 515. Relay 515 opens the rotary circuit at armature 576 and connects its lower winding in series with the rotary magnet to hold the relay operated. Due to the resistance of the relay, however, magnet 517 does not operate. In the same manner as in local connections, relay 515 shunts at its upper winding at armature 575 thereby placing direct ground on test conductor 165, opens the vertical magnet circuit, and short circuits the lower winding of relay 509 at armature 577, and at armatures 574 and 578 it opens the original energizing circuit of relay 511, and closes the control loop including the lower winding of relay 511 through to the connector switch by way of the two talking conductors of the trunk. In the connector, relay 302 operates and locks to ground on release trunk conductor 165, and also disconnects the non-inductive resistance 313. Common holding conductor 320 is grounded at armature 330. A circuit for impulsive relay 307 of connector C may now be traced from battery, lower winding of relay 511, armatures 535, 554, and 546, lower right-hand winding of repeating coil R2, armature 578, wiper 583, trunk conductor 164, armature 326, winding of relay 307, upper winding of relay 306, contacts controlled by armature 348, armatures 341, and 321, conductor 166, wiper 580, armatures 574 and 566, upper right-hand winding of repeating coil R2, to ground by way of armature 544. Relay 511 remains operated over the above circuit when its original energizing circuit is opened at contacts controlled by armature 578. Relay 307 operates in series with relay 511, but relay 306 does not operate when its upper winding alone is energized. It may be noted, however, that current flow is now in the opposite direction to the current flow in the relay when the switch was seized in a local connection. The purpose of this will be made apparent in later paragraphs. Relay 307

when operated prepares the impulsive circuit at armature 355.

The operator now dials the next to the last digit, in this case the digit 2, and the circuit of relay 503 is interrupted as in the previous instance. Relay 503 responds and in turn opens the control loop over which relay 307 operated at armature 535, at the same time closing a temporary holding circuit for relay 511. Relay 509 of the transmission selector again operates during the series of impulses and replaces the ground at armature 544 by ground at armature 553 to improve the impulsive. Relay 307 responds to the interruptions produced in the control circuit by relay 503, and on dropping back for each impulse, closes a circuit from ground, armature 330, conductor 320, contacts controlled by armature 355, armatures 325, 344, and 335, through the winding of vertical magnet 308 to battery. The vertical magnet responds to the impulses and raises the wipers of the switch two steps opposite the second level. Relay 304, which is connected in parallel with the vertical magnet, also operates and at armature 339 opens a point in the operating circuit of relay 303. Shortly after the last impulse of the series, relay 304 drops back and closes a circuit for relay 303 extending from ground on the common holding conductor, armature 355 (relay 307 now remaining operated), off-normal contacts 317 closed on the first vertical step of the wipers, armatures 343 and 339, through the winding of relay 303 to battery. Relay 303 operates, locks itself to ground on release trunk conductor 165 at armature 333 and disconnects relay 302 from the release trunk; connects additional ground to common holding conductor 320 at armature 334 by way of off-normal contacts 316 which close on the first vertical step of the wipers; switches the impulsive circuit from the vertical to the rotary magnet at armature 335; and prepares a locking circuit for relay 301 at armature 336. Ground on the release trunk conductor which caused the operation of relay 303 now extends by way of resistance 314 through the lower winding of relay 306 to battery. As previously mentioned, relay 306 is a polarized relay and does not operate over either winding alone or when the upper and lower windings oppose each other. As previously stated, the direction of current flow in the upper winding of relay 306 is now such that the upper and lower windings assist each other and, consequently, the relay operates and short circuits resistance 314 at armature 351 to complete a locking circuit for its lower winding; opens the control loop extending from ground at armature 544 of the transmission selector and connects ground at the connector to the battery side of the control loop at armature 348; closes a new locking circuit for relay 302 at armature 350; closes the ring

control circuit at armature 352; and at armature 353 opens a point in the busy tone circuit. Relay 511 of transmission selector TTS and relay 307 of connector C are now held 5 operated in series over trunk conductor 164.

The operator now dials the final digit of the called number, again the digit 2, and relay 503 responds as previously. The circuit of relay 307 is interrupted twice at armature 10 535 and relay 307 responds as before. Relay 511, however, remains operated over the holding circuit closed at contacts controlled by armature 535. Relay 307 now transmits two 15 impulses, this time to the rotary magnet 309 which was connected up by the operation of relay 303. Relay 304 again operates from the impulses, connects up busy test relay 305 at armature 338, and closes an additional point in the impulsive circuit at armature 340, 20 shunting armature 344 to prevent interference from relay 305 should that relay momentarily operate as the wipers pass over a busy contact. Magnet 309 responds in the usual way and steps the wipers 356-358 around 25 to the contacts of the called line, in this case contacts associated with line comprising conductors 359-361, terminating in sub-station T2.

The line may be idle, busy in a toll connection, or busy in a local connection. When an idle line is connected with, there will be no ground on the test contacts of the called line and relay 305 in connector C will not operate. Shortly after the last impulse of 30 the final digit, relay 304 will restore and close a circuit from ground on common holding conductor 320, armature 355, off-normal contacts 317, armature 343, upper winding of relay 301, armatures 345, 354, and 338, test 35 wiper 357, trunk conductor 360, thence through the cut-off relay of the associated line switch to battery. The cut-off relay (corresponding to relay 4 of line switch LS) and relay 301 operate in series over the above circuit. Relay 301 connects the talking conductors through at armatures 320 and 327 to prepare the ringing circuit, prepares the ring-back tone circuit at armature 321, connects ground through resistance 311 to the 40 test wiper by way of armature 322 to mark the called line toll busy for purposes to be explained hereinafter, connects its lower winding in series with vertical magnet 308 at armature 324, prepares a locking circuit 45 for relay 302 at armature 325 which will be effective later, and opens the control circuit over which relays 511 and 307 were held up at armature 326. Relay 307 restores, opens a point in the test circuit at armature 354 50 and closes another point in the holding circuit for relay 302 at contacts controlled by armature 355. Returning now to toll transmission selector TTS, relay 511 restores, opens a point in the circuit of relay 505 at 55 armature 555, and closes a circuit from

ground on common holding conductor 585, off-normal contacts 524 closed on the first vertical step of the wipers, interrupter contacts 536, armatures 552 and 556, contacts controlled by armature 545, winding of relay 508 to battery. Relay 508 operates and locks itself to ground on conductor 585 at armature 545; disconnects busy test relay 514 from wiper 581 at armature 541; connects balanced relay 504 in series with the two windings of impulse relay 503 by way of the reversing contacts of relay 505 at armatures 542 and 547; opens the holding circuit of relay 512 which now restores, having no function to perform at this time; connects alternating current relay 506 in bridge across the incoming trunk conductors in series with condenser 584; disconnects ground from the upper talking conductor at armature 544, thereby removing the shunt from the upper winding of relay 511; closes an additional circuit for the lower winding of relay 511, this time by way of armatures 572 and 546 instead of by way of armature 554; and opens a point in the busy tone circuit of armature 548. Relay 503 remains operated over the loop from the operator's position, but relay 504 does not operate as its two windings are arranged to oppose each other.

The operator receiving no busy tone will 95 now withdraw the plug of dial cord DC from jack J1 and relay 406 will restore and again connect the trunk conductors through to the trunk relay group RCT. Relay 402 is now held operated over its lower winding and the sleeve of jack J and the plug of the answering or toll cord AC. The loop for holding relay 503 now extends by way of contacts controlled by armature 416, upper right-hand winding of repeating coil R1, through the winding of polarized relay 401, armature 408, lower right-hand winding of repeating coil R1 and contacts controlled by armature 418. The direction of current flow in the operator's loop is in such direction that relay 401 operates and at armature 407, closes a circuit for lamp L. Lamp L lights and gives the operator "line seizure" supervision.

When the operator desires to ring the called subscriber, a momentary operation of the ringing key K of the toll cord circuit connects alternating current to the talking conductors and through the left-hand windings of repeating coil R1. This current is induced in the right-hand windings of the repeating coil and is transmitted over the trunk conductors to relay 506 of toll transmission selector TTS which responds. Relay 504 which is now connected in series with relay 503 across the trunk has a relatively high impedance and prevents the ringing current on the trunk from interfering with the operation of relay 503. Relay 506 on operating, closes a circuit for relay 507 at armature 540. Relay 507 operates, connects ground at arma- 100 105 110 115 120 125 130

ture 587 by way of wiper 581, trunk conductor 163, armatures 352 and 346, through resistance 312 to battery, thus shunting relay 302 which restores. Relay 302 now completes the ringing circuit at armatures 328 and 332 and opens its own locking circuit at armature 331. Ringing current is now sent out over the called line in exactly the same manner as on local calls and the bell 10 at the called sub-station T2 is operated. Ring-back tone is given to the operator through condenser 319 which is connected to the upper talking conductor by way of armature 321. When the called subscriber 15 answers, a direct current circuit is closed over which relay 302 operates in the usual way and again closes its own locking circuit at armature 331, and opens the ringing circuit at armatures 328 and 332, at the same 20 time closing the talking circuit at the latter two armatures. In the transmission selector relay 511 now operates over a circuit extending from battery, lower winding of relay 511, armatures 535, 572, and 546, lower right-hand winding of repeating coil R2, armature 578, wiper 583, trunk conductor 164, armatures 332 and 327, wiper 358, line conductor 361, through the loop at the sub-station T2, line conductor 359, wiper 356, armatures 320 25 and 328, trunk conductor 166, wiper 580, armatures 574 and 566, upper right-hand winding of repeating coil R2, armatures 569 and 588, through the upper winding of relay 511 to ground. The two right-hand windings 30 of repeating coil R2 are now connected together by way of armature 549 and condenser 590 to provide a talking path. Relay 511 supplies the talking battery to the called subscriber. Relay 511 on operating closes 35 a circuit which may be traced from ground on common holding conductor 585, off-normal contacts 524, armatures 555 and 543, through the winding of relay 505 to battery. Relay 505 operates and by means of the usual 40 reversing arrangement, reverses the flow of current over the conductors of the trunk extending to the operator's position. The direction of current flow in relay 401 is such that that relay now restores and opens the 45 circuit of lamp L which ceases to burn and thus gives the operator the usual "answer" supervision.

When the conversation is finished, the subscriber at sub-station T2 replaces his receiver 50 and opens the loop over which relay 511 is held operated and that relay restores and opens the circuit of relay 505. Relay 505 restores and reverses the direction of current flow back to normal and relay 401 of the 55 trunk relay group RCT again operates and closes the circuit of lamp L. Lamp L now lights to inform the operator that a called subscriber has hung-up, that is, to give the "disconnect" supervision. The operator now 60 withdraws the plug of the toll cord from the

jack, and relay 402 restores and opens the circuit of relay 503. Relay 503 restores and opens the circuit of relay 502 which also restores and removes ground from common holding conductor 585. Relays 508 and 515 70 now restore and the circuit to the connector is opened. Relay 502 closes a circuit for the release magnet extending from ground by way of armature 532, off-normal contacts 523, through release magnet 518 to battery. The release magnet operates and restores the switch wipers to normal in the usual way. In connector C, the removal of ground from the common holding conductor of the toll transmission selector opens the circuit of relay 503 and that relay restores and opens the circuit of relay 501 which also restores. Relay 501 now opens the holding circuit of relay 302 which restores as does relay 306. A circuit is closed from ground by way of off-normal contacts 316, armatures 334 and 329, through the winding of release magnet 310 to battery. The release magnet operates and restores the wipers of the connector to normal in the usual way. All the apparatus involved in the connection has now returned to normal idle position and is in readiness to receive another call. 80

When a toll call, such as has just been described, is extended to a line which is busy in a local connection, the sequence of operations is somewhat different than in the just described instance. The busy line may be engaged in either an outgoing or incoming call, that is, may be the line from which a local call originates or the line to which some other local subscriber has extended a connection. In either case, there will be a direct ground connected to the test contact of the line, in the first instance the ground coming from the local first selector repeater, such as the selector SR of Fig. 1, and in the latter instance, from a connector such as the connector C of Fig. 3. 90

It will be recalled that during the operation of toll transmission selector TTS, relay 512 operated and locked following the first series of impulses dialled by the operator, and that relay 511 was held up over its lower winding in series with line relay 307 and relay 306 of connector C by ground at armature 348 at the connector after the first series of impulses dialled into the connector. Now, when the wipers of connector C are stepped into engagement with the contacts of a busy line and before slow relay 304 restores after the series of impulses, a circuit is closed for busy relay 305 to ground on the test contact of the called line. Relay 305 operates, closes a point in its own locking circuit at armature 342, and closes a circuit which may be traced from battery, relay 514, resistance 521, armature 541, wiper 581, trunk conductor 163, to connector C, (relay 508 not having operated at this time) armatures 352 100 and 353. 105

110

115

120

125

130

and 346, upper winding of relay 301, armature 343, off-normal contacts 317, armatures 355 and 334 to ground at off-normal contacts 316. Relay 514 operates over the above circuit; completes a locking circuit for itself by way of armatures 567 and 561, off-normal contacts 524, to ground on common holding conductor 585; closes a discriminating test circuit at armature 566; prepares a circuit 5 for relay 510 at armature 570; opens the original energizing circuit of relay 512 at armature 571; opens a point in the alternate holding circuit of relay 511 at armature 572; and closes a point in the busy tone circuit at armature 573. Relay 301 of the connector does not operate over this circuit, however, due to the value of resistance 521. When relay 304 falls back shortly after the last impulse of the series, a circuit is closed from direct 10 ground on the test contact of the called line, wiper 357, armatures 338, 354, 349, 341, and 321, trunk conductor 166, wiper 580, armatures 574, 566, and 557, through resistance 589, to battery. Relay 512 is shunted by the 15 ground over the above traced circuit and restores, opens its own locking circuit at armature 559, opens a point in the discriminating test circuit, and closes a point in the talking circuit at armature 557, closes a point in the 20 circuit of relay 510 which will become effective at a later stage of the call, and disconnects the toll busy tone from the busy lead and substitutes the local busy tone at armature 560. The busy tone is impressed on the 25 lower talking conductor by way of armatures 573 and 548, through the lower windings of repeating coil R2, and is induced in operator's calling loop which extends through the left-hand windings of the repeating coil. 30 This tone informs the operator that the connection is temporarily prevented due to the called line being engaged in a local connection. It is unnecessary for the operator to know whether a line is calling or being called. 35 The operation of cutting in on the busy line and of effecting a disconnection being the same in either case.

Having been advised that the called line is locally busy, the toll operator will now 40 dial a digit, for example the digit 1 will suffice, and the circuit of relay 503 is interrupted in the usual way. Relay 503 on falling back closes a momentary circuit for relay 509 which energizes and due to its slow 45 releasing characteristics, maintains its armatures actuated for some time after the impulse or series of impulses. Relay 509 on operating connects relay 510 to test wiper 581 by way of armatures 550, 558, and 570, and the 50 wiper as previously described is engaging the contacts associated with conductor 163 which extends through the upper winding of relay 301 in the circuit previously traced for operating relay 514. Relays 510 and 301 55 now operate in series. It should be noted

here, that resistance 521 is connected between the above traced cut-in circuit and the locking ground for relay 514. This resistance prevents the ground at the toll transmission selector from shunting relay 301. Relay 510 70 on operating opens the holding circuit of relays 511 and 307 at armature 554, the alternate circuit of relay 511 having previously been opened at armature 572. In connector C relay 301 on operating closes points in the talking circuit at armatures 320 and 327, connects ground to the test wiper by way of resistance 311 at armature 322 to mark the line toll busy, opens the locking circuit of relay 305 at armature 323, locks its lower 75 winding in series with vertical magnet 308 at armature 324, and at armatures 326 and 321, disconnects relay 307 from the operating circuit. Returning to the transmission selector, relay 511 on releasing closes the circuit of relay 508 at armature 556. Relay 508 80 operates and switches over the transmission selector from operating position to talking position as previously described for a call to an idle line. In the connector relay 85 307 restores and disconnects wiper 357 from the upper talking conductor at armature 354. Busy relay 305 restores, opens a point in its own locking circuit at armature 342, and closes a point in the ring-control circuit at 90 armature 346.

The operator may now talk with the subscribers using the wanted line. Talking battery is supplied to the busy line by a selector such as selector SR whether the line is calling or being called, and it is not necessary to supply battery from transmission selector TTS. The talking loop from the transmission selector is in effect bridged across the talking conductors of the wanted line, the circuit extending from the upper contact of the line, wiper 356, armatures 320 and 328, trunk conductor 166, wiper 580, armatures 574 and 566, upper right-hand winding of repeating coil R2, armature 549, condenser 590, lower right-hand winding of repeating coil R2, armature 578, wiper 583, conductor 164, armatures 332 and 327, wiper 358, to the lower terminal of the wanted line. Battery for that portion of the trunk extending from the operator's position to the toll transmission selector is fed through relays 503 and 504 via the left-hand windings of repeating coil R2. The operator will inform the subscribers that a toll call is waiting and request them to hang up. The operator will also actuate the key K3 of the dialling cord DC (Fig. 4). When the subscribers hang up, the local switches are released in the regular way. If they do not hang up immediately, the operation of the key K2 will automatically cause the switches engaged in the local connection to restore as will be explained.

The operation of key K3 connects ground 130

to both sides of the trunk in parallel. Relay 503 of the toll transmission selector holds up over its lower winding, and 504 being unbalanced by having its upper winding shunted by the ground on the upper talking conductor now operates. Relay 504 closes a circuit from ground, armatures 529 and 537, relay 507 to battery. Relay 507 operates, closes a circuit from ground, armatures 586 and 568, through the lower winding of two step relay 513 to battery. Relay 513 is adjusted so that it actuates only its armatures 562, 563, and 564 when energized over the above traced circuit. A circuit may now be traced from ground, armatures 586 and 568, thence in two parallel paths by way of armatures 563 and 565, armatures 569 and 572, armature 546, right-hand windings of repeating coil R2, armature 557, armature 566, armatures 574 and 578, wipers 580 and 583, trunk conductors 164 and 166, armatures 328 and 332, armatures 320 and 327, wipers 356 and 358, through the upper and lower contacts of the called line.

Referring back to the operation of selector SR in a local connection, it will be recalled that talking battery is supplied from this selector to a calling line through relays 102 and 101, and to a called line through relays 102 and 103, and that furthermore, relays 101 and 103 were operated during the talking period and that balanced relay 102 was unoperated. The direct ground connected to the two sides of the line as described above holds up the respective battery feed relays and at the same time shunts one winding of the balanced relay (corresponding to relay 102 of selector SR) and that relay operates. A release circuit is thereby closed at armature 124 and the local selector and the connector engaged in the local connection are released as in the previously described local connection.

The operator maintains key K3 actuated for a short time and then allows the key to return to normal position which removes the ground from the two sides of the trunk. Relay 504 again restores to normal and opens the circuit of relay 507 which also restores and opens the original energizing circuit of relay 513. Relay 513 now operates in its second step over its two windings in series to ground on conductor 585 by way of armature 564; opens the locking circuit of relay 514 at armature 561; and opens a point in the previously traced control loop at armature 565. Relay 514 restores and closes a point in the usual talking circuit at armature 566, and connects up relay 511 to the control loop at armatures 572 and 569. In case the called subscriber has remained on the line, relay 511 will now operate over the called line loop as previously described, and relay 505 will operate to give the operator "answered" supervision. From this point the call proceeds

in exactly the same way as a call to an idle line as previously described. If the called party has hung up, relay 511 is not operated at this time, and when the dialling cord is disconnected, the operator receives the "line seizure" supervision, that is, lamp L lights in the usual way. The operator may start the ringing by operating the ringing key of the toll cord whereupon the ringing relay of the connector falls back and automatically connects ringing current to the called line. The call then proceeds as in the previous case.

In the event that the called line is busy in a toll connection, a connector such as connector C will be in engagement with the wanted line which will be marked busy by a ground on the test contact through a resistance such as resistance 311 in connector C (Fig. 3). In the transmission selector, when the connection has been extended to a line and relay 514 has operated, the discriminating test circuit for relay 512 will complete as before. In this case, however, the value of the resistance (corresponding to resistance 311) is such, that relay 512 is not shunted and, therefore, does not release. Consequently, if the operator now dials to cut in, relay 510 will not operate as its circuit is broken at armature 558. The operator receives a distinctive tone by way of the toll busy lead, armatures 560, 573, and 548 and the lower right-hand winding of repeating coil R2, the tone being induced in the left-hand windings of the repeating coil through which the operator's control loop circuit extends to the line relay of the transmission selector.

The release of the connection when a busy line was called is brought about by the disconnection of the cord circuit at the toll board. Relay 503 restores and opens the circuit of relay 502 which restores. Relay 502 closes the circuit of release magnet 518 at armature 532 and the magnet operates to restore the switch wipers to normal position. Relay 502 also removes ground from local holding conductor 585 permitting the release of relays 514, 512, and 515 and the toll transmission selector is now in readiness to receive another call. The connector releases in the usual way when ground is removed from the holding conductor at the transmission selector.

If the wanted line were busy in a connection extended by a local subscriber in another exchange, an incoming selector such as the selector ISR (Fig. 6) would be involved. In such connections this switch feeds talking battery to the called subscriber through relays 608 and 607. Referring to the previous description of the operation of the switch, it will be noted that relay 607 is operated over the called subscriber's loop and that relay 608, which is a balanced relay, is not operated. Switch-over relay 606 will also be normal since the relay is arranged to restore

when the connection is extended to the line.

Now, when ground is connected to the two talking conductors of the wanted line by the toll connector, the balance of relay 608 is upset and that relay operates. A holding circuit is closed for relay 607 extending from ground, armature 637, contacts controlled by armature 650, armatures 651 and 629, through the upper windings of relays 607 and 608 to battery. An additional holding circuit for relay 603 is closed at armature 638, and the release trunk extending over wiper 647 is opened at armature 639. This permits the release of the local connector involved in the connection which restores in the usual manner and thus frees the wanted line. The equipment in the other exchange, however, remains operated and the calling subscriber is expected to hang up and release the connection in the usual manner.

Toll call to subscriber at sub-station T4

In calling a subscriber such as the subscriber at sub-station T4 in office "B", the operator is required to dial the complete directory number of the line. As in the previously described connection, it will be assumed that the number of the wanted line is 3322.

By way of example, the extension of a call over the trunk terminating in trunk relay group RCT and toll transmission selector TTS will be described. The operator connects up the regular toll cord and dialling cord DC as for a connection to a subscriber in the "A" office. The first digit of the called number, that is the digit 3, is then dialled. Toll transmission selector TTS responds to the first digit in the usual way, and the wipers are advanced to the third level. Selector TTS then cuts in and selects an idle trunk in the usual way, for example the trunk comprising conductors 173-175, terminating in incoming selector ISR1 (Fig. 8). Switching relay 515 of selector TTS operates when this idle trunk is selected and connects up the control loop in the usual way. It should be noted, however, that the ring control circuit normally extending over wiper 581 is not connected up in this instance, and consequently there is no circuit for busy test relay 514. Cut-off relay 712 of the alarm signal relay group ASR (Fig. 7) and cut-off relay 601 of incoming selector ISR (Fig. 6), operate exactly as described for local inter-office connections, the latter relay disconnecting the selector ISR from the trunk.

The control loop from transmission selector TTS may now be traced from battery, lower winding of relay 511, armatures 535, 554, and 546, lower right-hand winding of repeating coil R2, armature 578, wiper 583, trunk conductor 173, armature 835, lower left-hand winding of repeating coil R, contacts controlled by armature 840, through the

upper windings of relays 802 and relay 805, normally closed contacts controlled by armature 841, upper left-hand winding of repeating coil R, armature 833, trunk conductor 175, wiper 580, armatures 574 and 566, upper right-hand winding of repeating coil R2 to ground at armature 544. Relay 802 of incoming selector ISR1 operates over the above traced circuit, closes a circuit for relay 303 at armature 888, and also closes a circuit from battery through the lower windings of relays 808 and 807, armatures 889, 891, and 844, lower right-hand winding of repeating coil R, normally closed contacts controlled by armature 879, through resistance 890 to ground. Relay 803 is connected in series with relay 810 and with the vertical magnet 817 in the same manner as the release relay of previously described selectors. Relay 803 operates but relay 810 and magnet 817 do not, due to the resistance of relay 803. Relay 803 connects ground to the local holding conductor at armature 837, and at armature 838 opens a point in the circuit of the release magnet. Relay 807 operates, its only function at this time being to open a point in the circuit of relay 804 at armature 851. Ground connected to the holding conductor at armature 837 now extends through resistance 822 and the lower winding of relay 805 to battery. It will be noted that the upper winding of relay 805 is energized in series with impulse relay 802, and that the direction of current flow in the present instance is opposite to that in the winding of relay 805 when the switch is seized for a local call. Relay 805 is adjusted so that it does not operate over its upper winding alone, or over its lower winding alone, when energized in series with resistance 822, nor does it energize when the two windings oppose each other as is the case on local calls. However, as previously mentioned, the direction of current flow in the upper winding of relay 805 is the reverse of that on local calls, and consequently, the relay operates. Resistance 822 is short circuited at armature 894, thus locking the relay up over its lower winding to ground on the common holding conductor. Supervisory circuits which will be described later on are prepared at armatures 846 and 847, and the circuit for relay 816 is closed at armature 848. Relay 816 now operates and reverses the connection of the talking conductors of the selector with respect to wipers 883 and 886 so that the current flow in the control loop extended to the local connector will be opposite to that obtaining in local connections. Relay 816 also prepares a circuit for relay 812 at armature 881.

The operator now dials the second digit, also the digit 3, and relay 503 of the toll transmission selector responds and opens the loop circuit to impulse relay 802 of incoming selector ISR1 in the usual way. Relay 802

responds to the interruptions, deenergizing and reenergizing three times. Each time relay 802 drops back, relay 803 is short circuited at contacts controlled by armature 888, and relay 810 and magnet 817 operate from the ground at armature 837. Magnet 817 steps the wipers of the switch up to the third level. Slow acting relay 810 operates in response to the first impulse and remains operated throughout the series of impulses; 10 opens a circuit connecting the two right-hand windings of repeating coil R at armature 854; closes a circuit for relay 812 at armature 857; and opens a point in the circuit of the rotary magnet at armature 858. Relay 812 operates and locks to ground on the common holding conductor by way of armatures 861 and 843. Shortly after the last impulse of the series, 15 relay 810 deenergizes and closes a circuit from ground on the common holding conductor, off-normal contacts 827 closed on the first vertical step of the wipers, interrupter contacts 831, armatures 858 and 877, interrupter contacts 832, through the winding of 20 rotary magnet 818 to battery. Magnet 818 operates, steps the wipers of the switch into engagement with the first set of contacts in the called level, and opens its own circuit at interrupter contacts 832. Magnet 818 continues to operate, buzzer like, interrupting its 25 own circuit and advancing the wipers step by step until the rotary circuit is opened by the operation of relay 815. When an idle trunk is found, for example the trunk comprising conductors 931-934, terminating in 30 connector C1, relay 815 operates in series with the ring cut-off relay (302) of connector C1 over release trunk conductor 933 of the trunk. Relay 815 on operating extends a control loop 35 from the selector ISR1 to connector C1 by way of wipers 883 and 886 at armatures 875 and 879. The original operating circuit of relay 807 is opened by the operation of armature 879 but the relay now is held up in series 40 with the line relay of the seized connector. Relay 815 also shunts out its own upper winding, closes a locking circuit for its lower winding in series with rotary magnet 818, disconnects vertical magnet 817, and short 45 circuits the lower winding of relay 810.

A thorough understanding of the subsequent operation will be had by keeping in mind the fact that connector C1 is identical with connector C previously described, and 50 that the operation of the connector in the instant connection is exactly the same as the operation of connector C as described for a toll call to sub-station T2.

The above mentioned control loop of selector ISR1 extends from battery, lower windings of relays 808 and 807 in series, armatures 889, 891, and 844, lower right-hand winding of repeating coil R, armatures 879 and 882, wiper 883, trunk conductor 934, upper winding of the toll switching relay (306)

and winding of the impulse relay (307) of connector C1, trunk conductor 932, wiper 886, armatures 880, 875, and 867, upper right-hand winding of repeating coil R to ground at armature 842. The impulsing relay of 70 the connector operates, and relay 807 of the selector remains energized over the above traced circuit. The toll switch-over relay (306) of connector C1 does not operate at this time, however, since only its upper winding is energized. 75

The operator now dials the third digit, that is the digit 2, and relay 503 of toll transmission selector TTS and relay 802 of selector ISR1 respond in the usual way. The latter 80 relay interrupts the control loop extending to connector C1 at armature 889, and the impulse relay of the connector responds accordingly. The wipers of the connector are advanced two steps to the second level. 85 Shortly after the last impulse of the series, the series relay (304) of connector C1 falls back and closes the circuit of the switch-over relay (303) which operates and locks to the release trunk conductor. The polarizing circuit of the lower winding of the toll switch-over relay (306) is also closed, and, since the current flow over the trunk is in the opposite direction to that obtaining in local calls from selector ISR1 due to the operated condition 90 of relay 816, the two windings of the toll switch-over relay assist each other, and that relay operates to prepare the connector for toll operation. In the selector, relay 810 again operates during impulsing but has no 100 function to perform at this time. Relay 807 is locked up over a temporary holding circuit during impulsing as was the case when the selector was originally operated.

The operator now dials the final digit of 105 the called number, that is the digit 2, and the impulses are repeated as in the previous digit to the impulse relay of connector C1. The wipers of the connector are now advanced into engagement with the contacts of the called line. The connector tests in the usual way, and if the wanted line is idle, switching relay (301) operates to connect up 110 the wipers and to disconnect the impulse relay of the connector from the loop extending from selector ISR1. The connector marks the line as toll busy in the usual way. In selector ISR1 relay 807 restores and closes a circuit for relay 804 at armature 851. Relay 115 804 operates; prepares the ring control circuit at armature 839; disconnects ground from the upper talking conductor of the selector at armature 842, thus removing the shunt from the upper winding of relay 807; disconnects impulse relay 802 of the selector 120 from the control loop extended from selector TTS; connects the two windings of relay 806 in series to trunk conductor 173 at armatures 840 and 841; locks itself to ground on the common holding conductor at armature 843, 130

at the same time opening its own original energizing circuit and a point in the temporary holding circuit of relay 807; closes an alternate point in the control loop to connector C1 by way of armatures 844 and 872 instead of by way of armature 891; and opens a point in the busy tone circuit at armature 845. Relay 806 now operates in series with the lower winding of relay 511 of selector TTS and 5 closes a holding circuit for the lower winding of impulsive relay 802 at armature 849. Relay 802 is thus held up to prevent the release of the connection at this time. In the transmission selector, relay 511 restores since the 10 resistance of the two windings of relay 806 reduces the current flow to a point where relay 511 cannot maintain its armatures operated. Relay 511 closes a circuit for relay 508 which operates and locks, and switches 15 over the toll transmission selector from operating condition to talking condition exactly as it did on the toll call to a subscriber in the "A" office. The operator then disconnects the dial cord and is given the usual 20 "line seizure" supervision.

When the operator desires to signal the called line, the ringing key K of the toll cord is actuated and alternating current is impressed on the trunk in the usual manner. 25 Relay 506 responds and closes a circuit for relay 507. Relay 507 operates and closes a circuit from battery, resistance 520, armatures 588 and 569, upper right-hand winding of repeating coil R2, armatures 566 and 574, 30 wiper 580, trunk conductor 175, thence to incoming selector ISR1, to armature 833, upper left-hand winding of repeating coil R, armatures 841, 846, and 850, through the winding of relay 809 to ground. Relay 809 35 operates and connects ground to the ring control conductor by way of armatures 853, 870, and 839 and wiper 884. The ring cut-off relay (302) of connector C1 is shunted, and restores to complete the ringing circuit. 40 Relay 807 of selector ISR1 operates over the called line loop, connects battery to trunk conductor 175 at armature 850, and short circuits the lower or high resistance winding of relay 806 at armature 851. Relay 511 at the toll transmission selector TTS now operates from the ground through the low resistance winding of relay 806 of selector ISR1. Relay 511 closes the circuit of relay 505, which operates and reverses the direction of current flow over the operator's trunk to give the usual "answered" supervision. 45 From this point the call proceeds ex-

actly the same as for a call to a subscriber in the "A" office.

When the operator receives the "disconnect" supervision, the plug of the toll cord is withdrawn from the jack and transmission selector TTS restores to normal as previously described. The circuit of relay 806 of selector ISR1 is opened and that relay restores and opens the holding circuit of relay 802 which also restores. The circuit of release relay 803 is opened, and that relay restores and closes the circuit for the release magnet at armature 838. The release magnet operates and restores the wipers of the selector to normal position. The release of connector C1 is exactly the same as that of connector C which was previously described. 50

If the wanted line had been busy in a local connection when the wipers of the connector were set on the contacts of the line, the sequence of operations would be as follows: Referring to the description, at the point where the wipers have just been set on the contacts of the called line, the circuit of the busy relay (305) of the connector is closed and the busy relay operates and locks in the usual manner. The ring control lead is thereby connected to ground through the upper winding of the switching relay (301) at connector C1, and extends by way of trunk conductor 931, wiper 884, armature 839, resistance 825, through the winding of relay 814 to battery. Relay 807 remains operated as in the previously described connection to a busy line. Relay 814 operates, but due to the value of resistance 825, the switching relay of the connector does not operate. Relay 814 on operating completes the discriminating test circuit at armature 867, prepares the toll break-down circuit and disconnects the battery feed relay 807 from the control loop at armatures 868 and 872, closes a point in the circuit of relay 811, at armature 869, closes a point in the circuit of relay 813 at armature 870, locks itself to ground on the common holding conductor at armature 871, this holding circuit not including resistance 825, opens a point in the original energizing circuit of relay 812 at armature 873, and closes the busy tone circuit at armature 874. Now when the series relay (304) of connector C1 falls back shortly after the last impulse of the series, the test wiper of connector C1 is connected by way of trunk conductor 932, wiper 886, armatures 880, 875, 867, and 859, through the resistance 887 to battery. Since the wanted line is busy in a local connection there will be a direct ground on the test contact engaged by the test wiper, and this ground extending back over the above traced circuit will shunt relay 812 and cause that relay to release. Relay 812 upon restoring, opens a point in the discriminating test circuit at armature 859, opens its own holding circuit at armature 861, and connects up the 95 100 105 110 115 120 125 130

local busy tone circuit at armature 862. This tone is now transmitted to the operator who is thereby informed that the wanted line is busy, and that the call in which it is engaged 5 is a local one.

To cut in on the busy line, the operator now operates the calling device of the dial cord, interrupting the circuit of relay 502, which in turn interrupts the circuit of relay 10 802. Relay 802 again falls back and short circuits the release relay 803, and relay 810 operates as previously. Relay 810 when operated, closes a circuit which may be traced from battery through the winding of relay 15 811, armatures 855, 860, 869, and 839, wiper 884, trunk conductor 931, and thence through the upper winding of the switching relay (301) of connector C1 to ground. Relay 811 and switching relay of the connector operate 20 in series over the above circuit. Resistance 825 is connected at a point between the ground to which relay 815 is locked up and the ring control conductor, and is sufficiently high to prevent this ground from shunting 25 the switching relay. The switching relay completes the talking circuit at the connector in the usual way. Relay 811 on operating opens the holding circuit of relay 807 at armature 891, and at armature 893 opens a point 30 in the circuit of the upper winding of that relay. Relay 807 restores and closes the circuit for switch-over relay 804. Relay 804 operates and switches over from operating condition to talking condition as was previously described. In the transmission selector, relay 511 also restores as before, as it is now connected in series with the two windings of relay 806 and selector ISR1, and selector TTS is switched over from operating 35 condition to talking condition in the usual way. The operator may now talk with the wanted subscriber over the toll connection which is bridged to the local connection as was explained for toll calls in the "A" office. 40 It should be noted that no battery is fed to the called line from selector ISR1 at this stage of the connection due to the operated condition of relay 814.

The operator will advise the wanted subscriber that a toll call is waiting and request that the local connection be released. If the subscribers hang up, the switches involved in the local connection will be released in the usual way. If they do not hang up, the 45 switches will be released automatically. After informing the wanted subscriber that a toll call is waiting, the operator will actuate key K3 of the dialling cord DC as before described, and connect ground to both 50 sides of the trunk. Relay 504 of transmission selector TTS which was connected in series with relay 503 by the operation of switch-over relay 508 is unbalanced by the ground on the trunk conductors and operates 55 to close a circuit for relay 507. Relay 507 op-

erates and closes a circuit from battery, resistance 520, armatures 588 and 569, upper right-hand winding of repeating coil R2, armatures 566 and 574, wiper 580, trunk conductor 175, armature 833, upper left-hand 60 winding of repeating coil R, armatures 841, 846, and 850, through the winding of relay 809 to ground. Relay 809 operates and closes a circuit from ground, armatures 853 and 870, through the lower winding of relay 813 65 to battery. Relay 813 which is a two step relay now operates in its first step, actuating armatures 864 and 865 but not the other armatures. During the time that the key K2 is held down, ground is connected to both 70 talking conductors by way of armatures 853, 870, and 864, thence in two parallel paths including armatures 863 and 866, armatures 868 and 872, armature 844, right-hand windings of repeating coil R, armature 867, armatures 875 and 879, armatures 880 and 882, wipers 883 and 886, trunk conductors 932 and 934, over the talking conductors and wipers of connector C1 to the contacts of the wanted line. The local switches engaged in the call 75 are released in the manner previously described for calls in the "A" office, since the balanced relay of the local selector corresponding to the relay 102 of selector SR is operated, or in the case of a local interoffice 80 call, the balanced relay corresponding to relay 808 of selector ISR1 is operated.

When the operator allows key K2 to return to normal, ground is removed from the trunk conductors and relay 504 restores to 100 open the circuit of relay 507. Relay 507 restores and disconnects battery from trunk conductor 175.

Relay 809 restores and disconnects the ground from the operating winding of relay 105 813. Relay 813 now operates in its second step over both windings in series to ground on the common holding conductor by way of armature 865. The break-down circuit is opened at armatures 863 and 866 and the circuit of relay 814 is opened at armature 895. Relay 814 restores and again connects relay 807 in bridge of the loop extending from selector ISR1 to the called line. A point in the talking circuit is closed at armature 867 110 and the busy tone is disconnected from the trunk at armature 874. If the wanted party has not hung up, relay 807 will immediately operate over the called line loop, and complete the usual supervisory circuit by connecting battery through resistance 823 to trunk conductor 175, and by short circuiting the high resistance lower winding of relay 806. If the called party has hung up, relay 115 807 will not be operated immediately and the operator on disconnecting the dialling cord from the jack will receive the usual "connected" supervision. In this case the operator will start the ringing of the connector 120 as in the previously described connection to 130

an idle line. From this point on, the sequence of operations including supervision and release, is exactly the same as in the previously described connection.

- 5 Had the wanted line been busy in a toll connection, the operation would be exactly the same as that described up to the point where the discriminating test conductor was connected to the upper terminal of relay 812.
- 10 As the line is busy in the toll connection, the ground on the test contact of the called line is fed through a resistance (corresponding to resistance 311 on connector C) by the toll connector involved in the connection. Relay 15 812 is not shunted due to the value of the resistance (311) and, therefore, remains operated. The operator now receives the toll busy tone by way of armatures 862 and 874, and is thus informed that the line is in use 20 for another toll call. Relay 807 will remain operated and consequently switching relays 804 of selector ISR1 and 507 of transmission selector TTS are not operated. If the operator dials or rings over the trunk this 25 will have no effect in the present stage of the call. Relay 810 of selector ISR1 will operate as in former instances, but relay 811 cannot operate as its circuit is open at armature 860. Ringing over the trunk will have no effect 30 since relay 506 of transmission selector TTS has not been bridged across the trunk conductors. To release the call, the operator withdraws the plug from the jack and the apparatus restores in a manner previously described.

The purpose of the resistance 824 and shaft controlled contacts 897 (shown in dotted line) is to adapt the selector ISR1 to operate as an intermediate selector on toll calls extended 40 to a third automatic exchange. The shaft contacts operate when the selector is operated to an outgoing level and connect relay 811 to the ring control lead. The trunk (not shown) will be similar in all respects to the 45 trunk comprising conductors 173 and 175 and the terminating switch will be the same as selector ISR1. Relay 811 will then be controlled by relay 809 and at armature 893 will connect battery via resistance 824 to the 50 upper trunk conductor to initiate the forced release operation and control the ring start circuit of the terminating selector in the same manner as is done by relay 507 of transmission selector TTS.

55 *Alarm signal in office "A"*

It is common practice in automatic telephone systems to provide various alarm signals, either visible or audible, for various un- 60 standard conditions of the apparatus. An unstandard condition may be a blown fuse, the failure of a switch such as a selector or a connector to properly release, the failure of a ringing tone or busy tone machine, the 65 failure of a charging generator, etc. Certain

of these unstandard conditions are far more serious than others due to the fact that a much larger amount of apparatus is rendered inoperative or possibly the service of the entire exchange is affected. In unattended automatic exchanges it is very desirable that these alarm signals be relayed to a point where there is someone in attendance, for example, the toll board or a manual exchange if there is such an exchange in the system. Special 70 trunks may be provided for this purpose. However, when there is a relatively great distance between the exchanges, it is usually more economical to provide equipment for transmitting these alarm signals over the 75 regular interoffice trunks. The manner in which this is done by means of the present invention will be described in detail in the following paragraphs.

Referring to Fig. 7, there is shown an 80 alarm signal relay group ASR which serves the double purpose of transmitting alarm signals in "A" office to the toll operator, and of relaying alarm signals from the "B" office to the toll operator. By way of illustration, 85 two of those alarm signals have been shown, the one designated "regular fuse" being one of the less important alarms, the other designated "emergency fuse" being one which requires immediate attention. The regular 90 fuse alarm consists of a number of alarm fuses such as fuse 768 connecting the regular exchange battery buss bar 766 with the various battery leads extending to individual pieces of apparatus. The alarm bar 767 is so placed 95 that when a fuse blows there will be a connection between the battery buss bar and the alarm buss bar. The emergency fuse arrangement is similar to the regular fuse arrangement and both are well known in the 100 art. The fuse alarm lead extending to relay 771 may also be common to a number of other fuse alarms or to alarms of other types if desired.

Consider first the condition of fuse 768 105 blowing from an over load or other case of trouble. A circuit is closed for relay 771 and that relay operates and at armature 773 disconnects battery from relay 705. Relay 705 which is normally operated retracts its 110 armatures, prepares a circuit for relay 706 at armature 731, opens a point in the relaying circuit at armature 732 to prevent interference by an alarm signal from the exchange "B", prepares a locking circuit for relays 702 and 703 at armature 733, and at armature 734 closes a circuit which may be traced from ground, upper winding of relay 703, armatures 723, 734, and 718, release trunk conductor 171, (Fig. 5) armature 528, through the winding of relay 501 to battery. Relays 703 and 501 operate over the above 115 circuit. The latter relay disconnects the transmission selector TTS from the trunk. Relay 703 closes a circuit from battery 120 125 130

through impedance 704, armatures 727 and 717, trunk conductor 172, then to the trunk relay group RCT (Fig. 4), and by way of contacts controlled by armature 418, lower 5 right-hand winding of repeating coil R1, armature 408, through the winding of relay 403 to ground. It will be recalled that a call to the operator was extended over the trunk in exactly the same manner, that is, by the 10 connection of battery to trunk conductor 172. Relay 403 operates and completes the usual circuit for signalling the operator for an incoming call. Relay 703 also connects a distinctive tone to trunk conductor 172 by way 15 of condenser 713, armatures 726, 727, and 717; connects direct ground to the release trunk at armature 728 to hold up the cut-off relay 501 of transmission selector TTS; at armature 729 closes a locking circuit for 20 its lower winding to ground at armature 733; and at armature 730, connects the upper winding of relay 702 to trunk conductor 170 by way of armature 722.

The operator on noting the call signal will 25 insert the plug of answering cord AC into jack J and operate the listening key of the cord circuit for the purpose of talking with the supposed calling subscriber. The tone impressed on the trunk, however, will inform 30 the operator that the call is due to an alarm signal and the fact that it has come in over this particular trunk will indicate that the signal is in the "A" office. To clear the trunk, the operator will momentarily insert the plug 35 of the dialling cord DC into jack J1 and momentarily operate relay 406. Relay 406 closes a circuit for relay 402 which operates and locks to the sleeve of the answering cord. When the dialling cord is withdrawn from 40 the jack, the trunk is extended to the relay group in the usual way, and a circuit may be traced from battery impedance 704, armatures 727 and 717, trunk conductor 172, contacts controlled by armature 418, lower right-hand winding of repeating coil R1, armature 408, through the winding of polarized relay 401, upper right-hand winding of repeating coil R1, contacts controlled by armature 416 45 trunk conductor 170, armatures 722 and 730, through the upper winding of relay 702 to ground. Relay 702 operates, opens the circuit of the two windings of the relay 703 at armatures 723 and 724, and at the latter armature completes a locking circuit for its own 50 lower winding to ground at armature 733. Relay 501 of transmission selector TTS now restores and again connects the selector to the trunk, and when the operator withdraws 55 the plug of the answering cord from the jack, the trunk is made available for regular calls. Referring now to the signal relay group ASR, it is obvious that relay 702 will remain energized as long as relay 705 remains normal, 60 that is, until such time as the alarm relay 771 has been cleared, or until such time as the operator has cleared the alarm.

The operator having been informed of an alarm signal from the "A" office now extends a connection over the trunk in the usual way, 70 by way of transmission selector TTS and a regular connector, such as the connector C (Fig. 3), to the special signal terminals accessible to that connector. These terminals may be reached by dialling a special number which is known only to the operator. When the wipers of the connector are set on this set of terminals, the switching relay of the connector operates from battery, through 75 the winding of relay 706, armatures 731 and 736, and test wiper 357 of the connector. The conductors 763 and 780 extend to contacts in the connector bank, the circles terminating these conductors in Figs. 7 and 3, designated respectively 769 and 770, indicate that the 80 similarly designated conductors of the two figures are connected. The connector, therefore, switches over to talking position, and relay 706 of the alarm signal relay group operates. This relay is made slow to operate 85 in order to allow sufficient time for the switching relay of the connector to become fully energized. Relay 706 closes a locking circuit for itself in series with relay 705, and also disconnects itself from trunk conductor 90 95 763. Relay 705 now energizes and releases the alarm signal relay group, including relay 702. When alarm relay 771 is operated, a distinctive tone, designated tone #1, is connected to the lower talking conductor of the connector by way of armature 772, conductor 780, and wiper 358. The operator is thus informed that the call, or rather the alarm signal, is due to some particular 100 unusual condition. It is obvious that any 105 number of different tones may be used by providing a number of relays such as the relay 771.

In case an emergency alarm signal comes in during the time that relays 705 and 706 are locked up or when those relays are normal, 110 relay 776 will operate in the usual way and open the circuit of relay 708. Relay 708 will close the same circuits which were previously closed by relay 705, and a call will be transmitted to the operator in exactly the same manner as in the previous instance. The operator will again clear the trunk and dial back the special number, this time the tone 115 #2 will be connected to conductor 780, and either alone or in conjunction with tone #1 will inform the operator of conditions in the exchange. When an alarm signal clears and relay 771 restores, the circuit for relay 705 is again closed and relay 706 is shunted. Relay 706 will restore and open its own locking circuit and the apparatus is again in normal 120 condition.

In case the trunk comprising conductors 170-172 has been in use when the alarm sig- 125 130

nal just described originated, there would be no circuit for the upper winding of relay 703 since conductor 171 would be grounded in the case of an incoming call, or the cut-off relay would be disconnected in the case of an out-going call. In this event the signal will be stored until such time as the trunk becomes available at which time the call would be extended to the operator in the manner just described. The trunk when used for signalling purposes is obviously made busy for other calls. This condition, however, is of very short duration since the operator can immediately clear the trunk as explained.

15 *Alarm signal in office "B"*

The manner in which an alarm signal in the "B" office is extended to an operator will now be described. Assume first, that an alarm signal is given in the "B" office, and the circuit of relay 937 is closed in the manner described for relay 771 in the previous connection. Relay 937 opens the circuit of relay 901 at armature 935, and at armature 936 connects tone #1 to conductor 941 extending to a contact in the connector banks. Normally operated relay 901 now deenergizes, closes points in the alarm circuit at armatures 911 and 914, prepares the circuit of relay 902 at armature 913, and at armature 912 closes a circuit for relay 905. The latter circuit extends by way of resistance 910, armatures 924 and 927, release trunk conductor 174" to incoming selector ISR1 (Fig. 8), armature 836 and winding of relay 801 to battery. The resistance 910 is of such value that relay 801 is not operated in the above circuit. Relay 905, however, operates and closes a circuit which may be traced from battery, resistance 40 909, armatures 914 and 922, trunk conductor 173, then to alarm signal relay group ASR (Fig. 7), normally operated armature 745, through the lower winding of relay 709 and resistance 715 to ground, and also by way of 45 battery and resistance 908 of relay group ASR1, armatures 911 and 921, trunk conductor 175, then to alarm signal relay group ASR, normally operated armature 744, through the upper winding of relay 709, resistance 714 to ground. Resistances 908, 909, and 714 and 715 are very high, and consequently the current flow over the trunk is reduced to a very small value. It may also be pointed out that relay 710 is normally 50 energized in series with cut-off relay 601 of the associated incoming selector ISR (Fig. 6) but relay 601 is not operated due to the value of resistance 716. Relay 709 closes a circuit for relay 701 at armature 743, and 55 at armature 764 completes the circuit for the upper winding of relay 703. Relay 701 operates and switches the alarm signal relay group from the trunk comprising 170—172 to the trunk comprising conductors 170'—172'. 60 Relay 703 operates in the usual way in series

with the cut-off of the associated toll transmission selector, and signals the operator over the trunk as previously described. The operator on answering the call is given the usual tone and then clears the trunk by operating relay 702 which locks to ground at armature 782. Since the signal comes in over the trunk comprising conductors 170—172', the operator is informed that the signal is extended from the "B" office.

70 The operator to determine the cause of the alarm now dials back the special number, using the same apparatus as for extending a toll call to a subscriber in the "B" office. Connector C1 is operated into engagement with the contacts associated with the special alarm conductors 941 and 942. The switching relay of connector C1 and the slow relay 902 operate in series over conductor 942 and the test wiper of the connector. A distinctive tone is given to the operator by way of armature 936 of the alarm relay 937 and conductor 941.

75 The case of an emergency alarm, a call is extended to the operator in exactly the same manner as that just described except that alarm relay 940 opens the circuit of relay 904 which performs the same function as relay 901 and tone #2 is transmitted to the operator.

80 It should be noted, especially, that the inter-office trunk is not made busy to the local selectors in the automatic exchange, and consequently the trunk is available for inter-office calls. When a selector, such as the selector SR1, seizes the trunk during the time an alarm signal is being transmitted there-over, relay 907 of relay group ASR1 will operate in exactly the same manner as if the trunk were not in use for signalling purposes. Relay 905 will be disconnected from the release trunk and consequently will open the alarm circuit at armatures 921 and 922, thereby causing the restoration of relay 709 and other relays of the relay group ASR (Fig. 7).

85 If the trunk is seized from the "A" office, by a selector such as the selector SR or a toll transmission selector such as transmission selector TTS, relay 712 of the alarm signal group ASR will operate and disconnect relay 710 from the series connection with the cut-off relay of selector ISR (Fig. 6). Relay 710 in turn will disconnect relay 709 and that relay will deenergize and clear the trunk extending to the operator. The call coming into the "B" office will operate incoming selector ISR1 (Fig. 8) in the usual way, and cut-off relay 801 will be disconnected from in series with relay 905 or relay group ASR1. This will cause the disconnection of the signal relay group ASR1 from the trunk. When the trunk again becomes idle, the alarm signal will again be transmitted to the operator in exactly the same way as previously described. 90 Alarm signals that have been cleared by the

operator dialling the special number, however, will not again come in but only those which have not as yet been answered or cleared by the operator.

5

All trunks busy

In the foregoing description of the various connections it was assumed that in each case an idle trunk was accessible to each selector involved in the connection. During periods of extra heavy traffic, all trunks of a particular group may become busy. When such a condition occurs, the operator or subscriber must be advised.

15 Referring first to Fig. 1, when the selector is operated to a called level as was previously described, the switch automatically rotates in on the called level and the wipers are stepped ahead until an idle trunk is found, or 20 until the wipers of the switch reach the eleventh position of the banks in which case they will be entirely free from the bank contacts. On reaching the eleventh rotary position, cam springs 115 and 119 will be operated mechanically by a cam on the shaft carrying the wipers. Contacts 119 on closing complete a circuit for the lower winding of switching relay 110 in series with vertical magnet 112, and the switching relay operates to open the 25 rotary circuit at armature 157. Switching relay 110 also opens the circuit of relay 103 which in turn opens the circuit of relay 106 and the selector switches over from operating to talking position in the same manner as on 30 a completed call. A busy tone will now be connected to the upper talking conductor of the selector by way of contacts 115 and armature 127. This tone will be the same as the busy tone used by the connector and is 35 audible to the calling subscriber who is expected to hang up and release the connection.

Referring now to Fig. 5, when the toll transmission selector TTS is operated to a level in which all trunks are busy, the switch 40 will automatically cut in and rotate in search of an idle trunk. When the wipers are stepped to the eleventh rotary position, the rotary contacts 525 and 526 will be operated, the former connecting a toll busy tone to the 45 lower talking conductor of the selector, the latter closing an operating circuit for the lower winding of switching relay 515 in series with vertical magnet 516. Switching relay 515 operates and opens the circuit of relay 511 in the usual manner and that relay 50 in turn closes the circuit of switch-over relay 508 which switches over the transmission selector from operating to talking position in the usual manner. The toll busy tone is 55 given to the operator in this case so that in case she does not note the tone before dialling the complete number of the wanted subscriber, she will then not attempt to cut in on the busy line. The toll busy tone may be 60 a tone similar to the local busy tone except

of a different frequency, so that the operator will be able to easily distinguish between the two.

The operation of selector ISR, Fig. 6, on encountering an all trunks busy condition is the same as that of the previously described selectors. Rotary eleventh position contacts 618 and 619 are operated, the former connecting the busy tone to the lower talking conductor of the switch, the latter completing an operating circuit for switching relay 609 which operates to open the rotary circuit. The local busy tone, that is the same busy tone as used for selectors such as SR and connector C, is used in this case since the switch is used only for local inter-office connections.

Combination toll and local incoming selector ISR1 (Fig. 8) operates in the same manner as the toll transmission selector TTS when an all trunks busy condition is encountered. In this case a toll busy tone is connected to the trunk so that the operator will not attempt to cut in on a busy line. Subscribers using this switch for interoffice calls will, of course, receive this toll busy tone, but it will be unnecessary for them to know that this is anything other than the regular busy tone.

What is claimed is:

1. In a telephone system, a selector repeater having access to local trunks and to outgoing trunks, means including said selector repeater and one of said trunks for extending connections to a subscriber's line, a busy test circuit in said selector repeater for determining the idle or busy condition of a called line, and a discriminating test circuit in said selector repeater for determining the class of connection in which a busy called line is engaged, said circuits being effective only when a call has been extended to a subscriber's line by way of a local trunk.

2. In a telephone system, a selector repeater having access to local trunks and to outgoing trunks for extending connections to subscribers' lines, a control circuit extending from the selector repeater effective only when a connection is extended over a local trunk, a second control circuit extending from the selector repeater effective only when a connection is extended over an outgoing trunk, and means for signaling called subscribers controlled over each of said circuits.

3. In a selector repeater for extending connections to subscribers' lines, a discriminating test relay energized responsive to the operation of the selector repeater in setting up a connection, a busy test relay energized responsive to the extension of a connection to a busy line, and means responsive to the operation of both said relays for short circuiting said discriminating test relay.

4. In a telephone system, an automatic

70

- switch, a trunk terminating in the switch, a double wound impulse relay for the switch, a bridge comprising the two windings of said impulse relay and battery and ground in series therewith normally connected across the conductors of said trunk, a second relay having two windings, means including the switch for extending a connection to a called line, and means responsive to the extension of such connection for connecting the two windings of said second relay in said bridge in series respectively with the two windings of said impulse relay.
5. In a telephone system, an automatic switch, a trunk terminating in the switch, an impulse relay for the switch having two windings normally connected across the conductors of said trunk in series with battery and ground respectively, a second relay having two windings, means including the switch for extending a connection to a called line, means responsive to the extension of such connection for connecting the two windings of said second relay in series respectively with the two windings of said impulse relay, and means for applying a characteristic potential to the conductors of said trunk to operate said second relay.
10. In a selector repeater having access to local trunks and to outgoing trunks, means for seizing one of said trunks and for transmitting impulses thereover to establish a connection with a called line, means effective when a connection has been established with a busy line via one of said local trunks for connecting a characteristic potential to the talking conductors of the trunk, and means effective when a connection has been established with a busy line via one of said outgoing trunks for transmitting impulses over the trunk.
15. In a telephone system, two exchanges, an incoming selector repeater in one exchange, a trunk connecting said exchanges and terminating in said selector repeater, local and toll automatic switches in the other exchange having access to said trunk, and means for adapting said selector repeater for either local or toll operation depending on whether the trunk is seized by a local switch or a toll switch.
20. In a selector repeater adapted to be seized in either a local or a toll connection, a ring control circuit for controlling the ringing relay of a succeeding switch, and means for rendering said circuit effective only when the switch is seized in a toll connection.
25. In a selector repeater adapted to be seized in either a local or a toll connection, wipers for extending connections, and talking conductors adapted to be connected to said wipers in either of two ways depending on whether the switch is seized in a local or a toll connection.
30. In a selector repeater for extending local or toll connections to subscribers' lines, a busy test relay energized when a local connection is extended to a busy line, and a switch-over relay energized when a toll connection is extended to a busy line.
35. In a selector repeater for extending local or toll connections to subscribers' lines, means for switching over the selector repeater from calling position to talking position when a local connection is extended to a busy line, and means for connecting up a busy tone when a toll connection is extended to a busy line.
40. In a selector repeater for extending local or toll connections to subscribers' lines, a busy test relay, and means for rendering
45. In a telephone system, a two way trunk terminating in an automatic switch, a branch of said trunk accessible to other switches, a cut-off relay normally connected to said branch, means responsive to an outgoing call over said trunk for operating said relay to disconnect said first switch from the trunk, and means responsive to an incoming call over the trunk for disconnecting said relay from said branch to mark said trunk busy to said other switches.
50. In a selector repeater equipped with talking and test wipers for extending connections, a discriminating test relay energized responsive to the operation of the selector repeater, a busy test relay energized over a circuit including one of said test wipers responsive to the extension of a connection to a busy line, and means responsive to the operation of both said relays for connecting said discriminating test relay to one of said talking wipers.
55. In a telephone system, a selector repeater for extending a connection to a line which may be busy in either a local or a toll connection, a discriminating test relay energized responsive to the operation of the selector repeater, a busy test relay energized responsive to the extension of the connection to the busy line, and a circuit for short circuiting said discriminating relay to cause the release thereof effective only when the called line is busy in a local connection.
60. In a selector repeater having access to local trunks and to outgoing trunks, means for seizing one of said trunks and for transmitting impulses thereover to establish a connection with a called line, means effective when a connection has been established with a busy line via one of said local trunks for connecting a characteristic potential to the talking conductors of the trunk, and means effective when a connection has been established with a busy line via one of said outgoing trunks for transmitting impulses over the trunk.
65. In a selector repeater adapted to be seized in either a local or a toll connection, a ring control circuit for controlling the ringing relay of a succeeding switch, and means for rendering said circuit effective only when the switch is seized in a toll connection.
70. In a selector repeater adapted to be seized in either a local or a toll connection, wipers for extending connections, and talking conductors adapted to be connected to said wipers in either of two ways depending on whether the switch is seized in a local or a toll connection.
75. In a selector repeater for extending local or toll connections to subscribers' lines, a busy test relay energized when a local connection is extended to a busy line, and a switch-over relay energized when a toll connection is extended to a busy line.
80. In a selector repeater for extending local or toll connections to subscribers' lines, means for switching over the selector repeater from calling position to talking position when a local connection is extended to a busy line, and means for connecting up a busy tone when a toll connection is extended to a busy line.
85. In a selector repeater for extending local or toll connections to subscribers' lines, a busy test relay, and means for rendering
90. In a selector repeater, a selector repeater for extending a connection to a line which may be busy in either a local or a toll connection, a discriminating test relay energized responsive to the operation of the selector repeater, a busy test relay energized responsive to the extension of the connection to the busy line, and a circuit for short circuiting said discriminating relay to cause the release thereof effective only when the called line is busy in a local connection.
95. In a selector repeater adapted to be seized in either a local or a toll connection, a ring control circuit for controlling the ringing relay of a succeeding switch, and means for rendering said circuit effective only when the switch is seized in a toll connection.
100. In a selector repeater adapted to be seized in either a local or a toll connection, wipers for extending connections, and talking conductors adapted to be connected to said wipers in either of two ways depending on whether the switch is seized in a local or a toll connection.
105. In a selector repeater for extending local or toll connections to subscribers' lines, a busy test relay energized when a local connection is extended to a busy line, and a switch-over relay energized when a toll connection is extended to a busy line.
110. In a selector repeater for extending local or toll connections to subscribers' lines, means for switching over the selector repeater from calling position to talking position when a local connection is extended to a busy line, and means for connecting up a busy tone when a toll connection is extended to a busy line.
115. In a selector repeater for extending local or toll connections to subscribers' lines, a busy test relay, and means for rendering
120. In a selector repeater for extending local or toll connections to subscribers' lines, a selector repeater for extending a connection to a line which may be busy in either a local or a toll connection, a discriminating test relay energized responsive to the operation of the selector repeater, a busy test relay energized responsive to the extension of the connection to the busy line, and a circuit for short circuiting said discriminating relay to cause the release thereof effective only when the called line is busy in a local connection.
125. In a selector repeater adapted to be seized in either a local or a toll connection, a ring control circuit for controlling the ringing relay of a succeeding switch, and means for rendering said circuit effective only when the switch is seized in a toll connection.
130. In a selector repeater adapted to be seized in either a local or a toll connection, wipers for extending connections, and talking conductors adapted to be connected to said wipers in either of two ways depending on whether the switch is seized in a local or a toll connection.

- said relay effective only when a toll connection is extended.
17. In a selector repeater for extending calls of two classes over a trunk, means for connecting a battery feed bridge to the trunk on calls for either class, and means for reversing the connection of said bridge with respect to the trunk on calls of one class. 70
18. In a telephone system, a selector repeater for extending local or toll connections, a trunk terminating in said selector repeater, means for connecting a source of current to said trunk to seize said selector repeater, and means controlled by the direction of current flow over said trunk for adapting the selector repeater for local or toll operation as required. 75
19. In a telephone system, an automatic switch, an incoming trunk terminating in said switch, means for connecting a source of current to said trunk to seize said switch, a plurality of trunks accessible to said switch, means for interrupting the current flow over said incoming trunk for operating said switch to seize one of said other trunks, means in the switch for connecting a source of current to the seized trunk, and means in the switch controlled by the direction of current flow over said incoming trunk for controlling the direction of current flow over the seized trunk. 80
20. In a telephone system, a connector switch for extending connections to subscribers' lines, a test wiper for said switch, a trunk comprising talking conductors and test conductors terminating in said switch, a switching relay energized over a circuit including said wiper when a connection is extended to an idle line, a busy relay energized over a circuit including said wiper when a connection is extended to a busy line, and means controlled by said busy relay for connecting said wiper to one of the talking conductors of said trunk and for connecting said switching relay to one of the test conductors of said trunk. 85
21. In a two digit responsive switch terminating a trunk, an impulse relay, a circuit for said relay comprising two conductors of the trunk in series effective to receive the first digit, and a circuit for said relay comprising only one conductor of the trunk effective to receive the second digit. 90
22. In a telephone system, a two digit responsive automatic switch, a trunk terminating in said switch, means for seizing the switch over two conductors of said trunk in series, means for transmitting the first directive digit to the switch over two conductors of said trunk in series, and means for transmitting the second directive digit to said switch over only one conductor of said trunk. 95
23. In a telephone system, a two digit responsive switch, a trunk terminating in the switch, an impulse relay for the switch, a circuit for said relay including two conductors of said trunk to which the two poles of a battery are connected respectively at a preceding switch, said circuit being effective to transmit the first directive digit, and a circuit for said relay including only one conductor of said trunk to which one pole of a battery is connected at a preceding switch and to which the non-corresponding pole of another battery is connected at the switch. 100
24. In a telephone system, two exchanges, a trunk line connecting said exchanges, means at one exchange for transmitting a continuous signal indicative of abnormal conditions in the exchange over one conductor of said trunk line to operate a visual indicator in the other exchange, and means controlled from the other exchange over two conductors of said trunk line in series for clearing the signal from said trunk line. 105
25. In a telephone system, two exchanges, a two conductor trunk connecting the exchanges, means for transmitting a continuous signal indicative of abnormal conditions in one exchange over one conductor of the trunk to the other exchange, means for simultaneously transmitting an intermittent signal indicative of the character of the abnormal condition over said one conductor, and means in the other exchange for momentarily connecting the two conductors of the trunk to clear the signals from the trunk. 110
26. In a telephone system, three exchanges, automatic means in the first exchange responsive to an unstandard condition for transmitting an alarm signal to the second exchange, and automatic means in the second exchange responsive to said alarm signal for transmitting an alarm signal to the third exchange. 115
27. In a telephone system, three exchanges, means in the first exchange responsive to an unstandard condition in that exchange for transmitting an alarm signal to the second exchange, and means in the second exchange responsive to an unstandard condition in either exchange for transmitting an alarm signal to the third exchange. 120
28. In a telephone system, three serially related trunk connected exchanges, means in the first exchange responsive to an unstandard condition in that exchange for transmitting an alarm signal to the second exchange via a trunk, and means in the second exchange responsive to an unstandard condition in that exchange for transmitting an alarm signal to the third exchange viz a particular trunk and responsive to the alarm signal from the first exchange for transmitting an alarm signal to the third exchange via a different trunk. 125
29. In a telephone system, a two conductor trunk terminating in an answering jack and a calling jack, a signal relay normally con- 130

nected to one conductor of the trunk and operated responsive to an incoming call over the trunk, a polarized relay normally disconnected from the trunk, and means responsive to an outgoing call over the trunk for disconnecting said signal relay from the trunk conductor and for bridging said polarized relay across the two trunk conductors.

30. In a telephone system, a first selector 10 repeater, a calling line, connectors accessible to said selector repeater for extending connections to signalling called subscribers on lines other than the calling line, a ring back switch accessible to said selector for signalling a called subscriber on the calling line, battery bridges in said selector repeater for supplying talking current to both calling and called subscribers when the connection is extended by way of a connector, and a battery bridge in said ring back switch for supplying talking current to both subscribers when the subscribers are on the same line.

31. In a telephone system comprising a manual toll exchange and intermediate and 25 terminating automatic exchanges, trunks extending from the manual exchange to a toll selector repeater in the intermediate exchange, local selector repeaters in the intermediate exchange, combination local and toll connectors accessible to all said selector repeaters, trunks accessible to all said selector repeaters extending to incoming combination local and toll selector repeaters in the terminating exchange, and connectors 35 accessible to said combination selector repeaters.

32. In a telephone system comprising a manual exchange and intermediate and terminating automatic exchanges, trunks extending from the manual exchange to toll selector repeaters in the intermediate exchange, local selector repeaters in the intermediate exchange, combination local and toll connectors accessible to all said selector repeaters in the intermediate exchange, trunks accessible to all said selector repeaters in the intermediate exchange, said trunks extending to incoming combination local and toll selector repeaters in the terminating exchange, local 45 selector repeaters in the terminating exchange, and combination local and toll connectors accessible to all selector repeaters in the terminating exchange.

33. In a telephone system comprising two 55 automatic exchanges, a two-way trunk connecting the exchanges terminating in an incoming selector repeater at the first exchange and terminating in an incoming combination local and toll selector repeater at the second exchange, local selector repeaters and toll selector repeaters at the first exchange having access to said trunk, and local selector repeaters at the second exchange having access to said trunk.

34. In a telephone system comprising two

automatic exchanges, a two-way trunk connecting the exchanges terminating in an incoming selector repeater at the first exchange and in an incoming combination local and toll selector repeater at the second exchange, 70 local selector repeaters and toll selector repeaters at the first exchange having access to said trunk, local selector repeaters at the second exchange having access to said trunk, and combination local and toll connectors in each exchange accessible to all selector repeaters in the same exchange.

35. In an incoming selector repeater adapted to be seized in either local or toll connections and for extending such connections over either local or outgoing trunks, a busy test circuit, and means for rendering said circuit effective only when a toll connection is extended over a local trunk.

36. In an incoming selector repeater adapted to be seized in either local or toll connections and for extending such connections over either local or outgoing trunks, talking and test wipers, a ring control circuit including a test wiper effective when a toll connection is extended over a local trunk, and a ring control circuit including a talking wiper effective when a toll connection is extended over an outgoing trunk.

37. In a selector repeater for extending connections to subscribers' lines via trunk lines of two classes, line wipers and a control wiper, means for applying a potential to the control wiper to effect the signalling of a subscriber's line connected with over a trunk line of one class, and means for applying a potential to one of the line wipers to effect the signalling of a subscriber's line connected with over a trunk line of the other class.

38. In a telephone system, a selector repeater for extending connections to subscribers' lines via trunk lines of two classes, line wipers and a control wiper for the selector repeater, a battery, means in the selector repeater for momentarily connecting one pole of said battery to said control wiper to effect the signalling of a subscriber's line connected with over a trunk line of one class, and means in the selector repeater for momentarily connecting the other pole of said battery to one of said line wipers to effect the signalling of a subscriber's line connected with over a trunk line of the other class.

39. In a telephone system comprising two exchanges connected by a trunk line over which talking connections may be established, a source of signalling current in one exchange, means in said one exchange for connecting said current source to the trunk line responsive to an abnormal condition in that exchange, means for disconnecting said current source from the trunk line responsive to the establishment of a talking connection thereover, and means for reconnecting said

current source to the trunk line responsive to the termination of the talking connection.

40. In a telephone system comprising two exchanges connected by a trunk line over which talking connections may be established, means for marking the trunk line busy when engaged in a talking connection, means in one exchange responsive to an abnormal condition therein for transmitting a continuous signal over the trunk line without marking the trunk line busy, and means for temporarily suppressing said signal when the trunk line is taken into use for a talking connection.

41. In an automatic switch adapted to extend calls of either of two classes, a battery feed bridge, a pair of wipers, and means for connecting said wipers to said bridge in either of two ways dependent upon the class of call extended.

20 42. In an automatic switch, incoming conductors and outgoing conductors, wipers, means for establishing current flow over said incoming conductors in either of two directions, and means for connecting said wipers to said outgoing conductors in either of two ways dependent upon the direction of current flow over said incoming conductors.

30 43. In an automatic switch, primary and secondary magnets, a switching relay, means for operating said magnets to set the switch, and means responsive to the completion of the setting of the switch for energizing said relay in series with one or the other of said magnets.

35 44. In an automatic switch, primary and secondary magnets, a switching relay, means including the magnets for operating the switch in its primary and secondary movements, means effective after a secondary movement of a certain extent for energizing said relay in series with one of said magnets, and means effective after a secondary movement of a different extent for energizing said relay in series with the other of said magnets.

40 45. In a telephone system, an automatic switch having access to groups of trunks, a primary magnet and a secondary magnet, a switching relay, means for operating the primary magnet to set the switch in selective relation with a group of trunks, means for operating said secondary magnet to cause the switch to test the trunks of said group successively, means responsive to the switch encountering an idle trunk for energizing said relay in series with said secondary magnet to prevent further secondary movement of the switch, and means responsive to the switch failing to find an idle trunk in the group for energizing said relay in series with said primary magnet to prevent further secondary movement of the switch.

50 46. In a telephone system, an automatic switch, a pair of wipers for the switch, a trunk 65 incoming to the switch, a battery, means in

the switch responsive to the unbalancing of the incoming trunk under certain conditions for connecting one pole of said battery to both of said wipers, and means in the switch responsive to the unbalancing of the incoming trunk under certain other conditions for connecting the other pole of said battery to one of said wipers.

70 47. In a telephone system, an automatic switch, a trunk incoming to the switch, two outgoing trunks accessible to the switch, a battery, means for operating the switch to extend a connection over either of said outgoing trunks, means for unbalancing said incoming trunk, and means responsive to the unbalancing of the incoming trunk for connecting one pole of said battery to both conductors of the outgoing trunk or for connecting the other pole of said battery to one conductor of the outgoing trunk dependent on which of said outgoing trunks is involved in the connection.

75 48. In a telephone system in which connections between calling and called parties are established over a train of automatic switches and in which talking current is supplied to both parties from the first switch of the train, means in the first switch of the train controlled by the calling party for maintaining all switches of the train operated during the connection, and means responsive to the withdrawal of the calling party from the connection for disabling said first means and for placing the release of the last switch of the train under the control of the called party.

80 49. In a telephone system in which connections between calling and called parties are established over a train of automatic switches and in which talking current is supplied to both parties from the first switch of the train, means responsive to the withdrawal of the calling party from a connection for releasing all except the last switch of the train and for adapting the last switch to supply current to the called party, and means including the current supplying means in the last switch of the train for maintaining said switch operated until the called party releases.

85 50. In a telephone system, a calling line and a called line, a switch, means for operating said switch to select the called line, a relay for said switch, means for energizing said relay in a local circuit to connect said lines, and means for energizing said relay in a circuit including the called lines responsive to the release of the calling line from the connections.

90 51. In an automatic switch, talking conductors, wipers, a relay for connecting the talking conductors with the wipers, a magnet for setting the switch, means for energizing said relay in series with said magnet in a local circuit, and means for energizing said

relay in series with said magnet in a circuit including said wipers and conductors outside of the switch.

52. In a telephone system, a calling line and a called line, an automatic switch, wipers for the switch, a wiper connecting relay, means controlled over the calling line for operating said switch to extend a connection to the called line, means for operating said relay in a local circuit to complete the connection through the switch, means controlled over the calling line for preventing the release of the switch, means responsive to the calling party releasing from the connection for disabling said release preventing means, for opening the local circuit of said relay and for completing a holding circuit for the relay over the called line, and means controlled by said relay for preventing the release of the switch until the called party opens said holding circuit by releasing from the connection.

53. In a telephone system, a calling line and a called line, an automatic switch, wipers for the switch, a magnet for the switch, means controlled over the calling line for operating said magnet to set the switch wipers in engagement with the called line, a relay in the switch for connecting the calling and called line via said wipers, means for connecting said magnet directly to said relay to energize the relay independent of the called line, and means responsive to the calling party hanging up for opening the direct connection between the relay and the magnet and for connecting the relay and magnet, respectively, to conductors of the called line whereby the relay is energized over the called line under the control of the called party.

40. In witness whereof, I hereunto subscribe my name this 26th day of September, A. D. 1929.

JOHN WICKS.
